APPARATUS FOR SIGNALING THE LOCATION OF RECESSES IN A FLOW CONDUCTOR

Norman F. Brown, Dallas, Tex., assignor to Otis Engineering Corporation, Dallas, Tex., a corporation of Delaware

Filed Oct. 21, 1965, Ser. No. 499,358
23 Claims. (Cl. 166—64)

ABSTRACT OF THE DISCLOSURE

A signaling device movable through a flow conductor for signaling the position of recesses therein and having laterally outwardly expandable sensor members movable on the mandrel between inner retracted positions and outer expanded positions, latch means engageable with the sensor means to prevent movement of the sensor means from expanded to retracted position until a predetermined movement of the mandrel relative to the sensor means has taken place to move the latch means out of latching position to permit the sensor means to move to retracted position. The mandrel is yieldably held against longitudinal movement relative to the sensor means to create a pressure signal indicating the engagement of the sensors of the device with the recess in the conductor. The device is designed for operation in either longitudinal direction, and for selectively rendering the device operative during movement in only one or the other of such longitudinal directions, if desired.

This invention relates to signaling devices and more particularly to a device for indicating the location thereof in a flow conductor during the movement of the signaling device through the flow conductor.

An object of this invention is to provide a new and improved signaling device, which may be connected to any suitable tool movable through a flow conductor, which requires an increase in the force moving the signaling device and the tool through the flow conductor when the signaling device moves past predetermined locations in the flow conductor to indicate such locations of the tool.

Still another object is to provide a signaling device which is movable through a flow conductor provided with longitudinally spaced internal annular recesses and having means engageable with the shoulders defining the recesses to increase the resistance to the movement of the signaling device through the flow conductor each time the signaling device moves past such recesses.

Still another object is to provide a signaling device which will operate properly when moved in either longitudinal direction through the flow conductor to provide a signal each time the signaling device moves past internal obstructions of the flow conductor located at known predetermined locations.

A further object is to provide a signaling device, connectable to a tool movable by liquid under pressure introduced into the flow conductor which produces shock and pressure waves in the liquid upstream thereof each time the signaling device moves past predetermined locations of the flow conductor.

Still a further object is to provide a signaling device having laterally outwardly expandable means which are movable into internal annular recesses of the flow conductor and having releasable latch means engageable with the expandable means to hold the expandable means in expanded positions.

Another object is to provide a signaling device wherein the latch means is moved to inoperative position to

2

permit movement of the expandable means back to their retracted positions to permit movement of the signaling device through the flow conductor by a force greater than that needed to move the signaling device through the flow conductor when the latch means is in inoperative position and the expandable means are not in their expanded positions.

Still another object is to provide a signaling device having a mandrel provided with a sensor means movable laterally on the mandrel between inner retracted positions and outer expanded positions, a latch means engageable with the sensor means to prevent movement of the sensor means from its expanded to its retracted position until the mandrel and latch means move a predetermined distance relative to the expanded sensor means to permit its movement to its retracted position, and means for yieldably resisting such movement of the mandrel and the latch means relative to the sensor means.

Still another object is to provide a signaling device wherein the means for yieldably resisting the movement of the mandrel and latch means relative to the sensor means comprises spring means.

Still another object is to provide a signaling device wherein the means for yieldably resisting such movement of the mandrel and the latch means relative to the sensor means comprises a hydraulic assembly.

A further object is to provide a signaling device having sensor means mounted on a mandrel which are movable laterally outwardly to expanded position to engage an internal obstruction of a flow conductor during the passage of the signaling device through the flow conductor, means for yieldably resisting the movement of the mandrel relative to the sensor means when the movement of the sensor means has been arrested, and means associated with the mandrel and the sensor means for holding the sensor means in its expanded position until the mandrel has moved a predetermined distance relative to the sensor means against the resistance of the resisting means.

A still further object is to provide a signaling device of the type described which has trigger means operatively associated with the resisting means and the sensor means which frees the mandrel from the resisting means to permit the movement of the mandrel relative to the sensor means after the mandrel has moved a predetermined distance relative to the sensor means.

Another object is to provide a signaling device having adjustable control means for selectively rendering the signaling device operative during its movement in one or the other longitudinal direction through a flow conductor and inoperative during its movement therethrough in the opposite longitudinal direction.

Additional objects and advantages of the invention will be readily apparent from the reading of the following description of a device constructed in accordance with the invention, and reference to the accompanying drawings thereof, wherein:

FIGURE 41 is a vertical fragmentary partly sectional view of a modified form of the spring assembly of the signaling device illustrated in FIGURES 29 and 30.

Referring now particularly to FIGURES 1 through 7 of the drawings, the signaling device 20 embodying the invention includes a central tubular mandrel 21 having a ball connector 22 secured to one end thereof and a socket connector 23 secured to the other end thereof. The ball connector has an inner reduced threaded portion or pin 25 which is threaded in one end portion of the tubular mandrel, an external annular flange 26 intermediate its ends which provides an inwardly facing annular shoulder or surface 27 which limits inward movement of the ball connector relative to the mandrel, a neck portion 28 and a ball 29.

The socket connector 23 has a first section 32 whose inner threaded portion or pin 33 is threaded in the opposite end of the mandrel, an external flange 34 intermediate its ends which provides an inner shoulder 35 which limits movement of the first section into the mandrel, and an outer externally threaded portion 38 which is threaded in the second section 40 of the socket connector. The socket connector sections 32 and 40 have spaced facing annular arcuate seat surfaces 41 and 42, respectively, between which a ball of a ball connector, such as the ball 29 of a ball connector 22, may be positioned for limited universal rotation therebetween. The neck of such ball connector will then extend outwardly through the passage or aperture 45 of the socket section 40.

A protector sleeve 50 disposed about the mandrel has two sections 51 and 52. The first sleeve section 51 extends between an external flange 53 of the mandrel and the external flange 34 of the first socket section 32. The inner edge portions of the first sleeve section are received in the recesses 54 of the mandrel flange. The outer end of the first sleeve section has an internal annular flange 55 which abuts the shoulder 35 of the flange 34 to limit outward longitudinal movement of the first sleeve section.

The second sleeve section 52 is disposed between the flange 26 of the ball connector 22 and the mandrel flange 53, its inner edges being received in the recesses 61 of the mandrel flange and its outer end being provided with an annular internal flange 64 which abuts the shoulder 27 of the ball connector flange 26 to limit outward longitudinal movement of the second sleeve section.

Each of the protector sleeve sections has circumferentially spaced pairs of long and short slots 65 and 66, respectively. The short slots of each sleeve section are aligned with the long slots of the other sleeve section. The four pairs of aligned short and long slots are also aligned with the longitudinal recesses 67 of the mandrel flange to provide two pairs of windows 68 and 68a.

The windows 68 extend longitudinally inwardly from 75 near the outer end of the sleeve section 52 and past the

mandrel flange in one longitudinal direction and the windows 63a extend longitudinally inwardly in the opposite direction from near the outer end of the sleeve section 51 and past the mandrel flange.

A pair of sensor or feeler members 70 extend outwardly through the windows 68. The inner ends of the sensor members are biased outwardly by a pair of flat springs 71 which extend longitudinally outwardly between the mandrel and the flange 54 of the sleeve section 53 and have laterally outwardly extending end portions 72 which are received in the recesses 73 of the sleeve section 53. The inner ends of the springs are received in the internal longitudinal extending recesses 74 of the sensor members. The sensor members are biased in one longitudinal direction by springs 77 whose inner ends bear against the external annular shoulders 78 of a pair of plungers 79 and whose lower ends bear against the surfaces 81 defining the ends of the recesses 82 provided in opposite end portions of a cross pin 84. The cross pin extends transversely through aligned elongate slots 85 of the two sensor members 70 and the aligned slots 86 of the mandrel. The upper ends of the plungers are provided with angular recesses 87 in which are received the angular portions of the keys defining the upper ends of the slots 85.

The inner ends of the sensor members 70 have external bosses 90 which provide inwardly divergent oppositely facing shoulders 91 and 92. The shoulders 91 extend at a smaller angle relative to the longitudinal axis of the signal device than the shoulders 92. The bosses are receivable in the internal annular recesses 95 of the locating nipples 99 connected at desired spaced locations in the string of tubing 100. The upper and lower annular shoulders or surfaces 96 and 97 of the locating nipple defining the top and bottom sides of the annular recess 95 may extend perpendicularly relative to the longitudinal axis of the locating nipple.

A second cross pin 84a extends laterally through the longitudinal slots 85a of the sensor keys 70a and the aligned slots 86a of the mandrel and the two cross pins are biased longitudinally away from one another by a pair of springs 110 and 111 which are disposed in the mandrel. One end of the outer spring 110 extends about the longitudinal guide extension 112 of the cross pin 84 and bears against its shoulder 113 and the other end of the outer spring extends about the similar guide extension 112a of the cross pin 84a and bears against its shoulder 113a. Opposite end portions of the inner spring 111 similarly extend about the guide extensions 114 and 114a and bear against the shoulders 115 and 115a of the cross pins 84 and 84a, respectively.

A pair of latch sleeves 116 and 116a slidably mounted on the mandrel on the opposite sides of its flange 53 are biased toward one another and toward the oppositely facing shoulders 118 and 118a of the flange by a pair of springs 119 which extend through diametrically opposite slots 120 of the flange. One hooked end of each spring 119 extends about a pin 122 rigidly secured to a pair of radially extending lugs 124 of the latch sleeve 116 and its other hooked end extends about a similar pin 122a carried by the lugs 124a of the other latch sleeve 116a.

The latch sleeve 116 has a pair of radially outwardly extending latch bosses 130 which, when the sensor members 70 are in the longitudinal positions on the mandrel illustrated in FIGURE 1, extend into the slots 131 of the sensor members and their upper surfaces or shoulders 134 engage the shoulders 135 defining the longitudinally inner ends of the slots 131. The engagement of the shoulders 134 and 135 holds the latch sleeve 116 in the longitudinally outward position illustrated in FIGURE 1 against the biasing force of the springs 119.

When the sensor members 70 move laterally outwardly to their outer or expanded positions illustrated in FIGURE 2, the latch sleeve 116 is moved inwardly by the force of the springs 119 until its movement is arrested by the engagement of its inner annular end surface with

the shoulder 118 of the mandrel flange. At this time the outer surfaces 140 of the latch bosses 130 abut the inner surfaces 141 of the sensor members 170 and lock the sensor members against direct return toward their retracted positions.

The beveled longitudinally outer cam shoulders 142 of the latch bosses are engageable with the similarly beveled shoulders 143 of the sensor members when the sensor members are moved longitudinally outwardly on the mandrel as will be explained below.

The latch sleeve 116a has opposed slots 144 in which inner portions of the sensor members 70 are received when the sensor members 70 are in their inner retracted positions illustrated in FIGURE 1. The sensor members 70 are also provided with internal recesses 145 in alignment with the mandrel flange and in which the latch bosses 130 are receivable. This permits the sensor members to move to their retracted or inner positions when the latch sleeve 116 is in its longitudinally outer position and also when it is in the innermost position abutting the mandrel flange shoulder 118.

The sensor members 70a and their latch sleeve 116a and their associated elements are identical in structure to the sensor members 70, the latch sleeve 116a and their cooperating elements, and, accordingly, the sensor members 70a, the latch sleeve 116a and their cooperating elements have been provided with the same reference numerals, to which the subscript *a* has been added as the corresponding elements of the sensor members 70, the latch sleeve 116 and their cooperating elements.

Referring now particularly to FIGURE 7 of the drawing, the locating device may be employed to position any suitable well tool T at a specific location in a string of well tubing 100 some of whose sections are connected by the usual coupling collars 160 and others of which are connected at predetermined known locations by the locating nipples 99. The well has a packer Q which closes the annulus A between the casing C and the tubing. The tubing has a valve section S having one or more lateral ports O above the packer Q which are openable by a valve sleeve V slideable in the valve section. The well has the usual casing head H provided with a pipe or conduit 161, having a valve 162 connected thereto by means of which, when the valve is open, fluid under pressure may be exhausted from the annulus. A pipe 164 conducting fluid, preferably an incompressible liquid, from a pump P, has two branches; one, controlled by valve 165, connected to the casing annulus and the other, controlled by valve 174, connecting to the tubing string 100. The tubing string 100 also has a vent pipe 160 closable by a suitable valve 167. A pressure sensing and recording device 168 of any suitable well known type senses and records the pressure and shock waves in the pipe 164 downstream of the pump P and therefore of the liquid operating the signaling device 20. The well also has the usual lubricator 180 connected to the usual valves 181 and 182.

The signaling device 20 is connected to a string or train of tools, such as the two or more sealing well tools 171 and 172 which sealingly engage the internal surfaces of the tubing. The signaling device is connected to the uppermost of the sealing well tools 171 by its ball connection 22. The two sealing well tools are also pivotally connected by a suitable ball and socket connection 173 which spaces the two sealing well tools from one another so that at least one of the sealing well tools is always in sealing engagement with the tubing, the connecting neck of the ball and socket connection being long enough to cause the two sealing well tools to span any coupling collar recess, locating nipple 99 or other internal recess in the string of tubing. The tool T is connected to the lowermost sealing well tool 172 by a suitable connecting means. The bosses 90 of the sensors are considerably longer than any internal recess of the string of tubing other than the recesses 95 of the locating nipples 99.

After closing valve 182 and opening the valve 181, the

tool T is inserted in the lubricator 180, followed by sealing well tools 171 and 172 and the signaling device 20. These four components are connected together by universal joints thus forming a tool string capable of passing through pipe bent to a radius as short as 60 inches. The two sealing well tools are preferably located in the lubricator below the level of pipe connections 164 and 166. Valves 181, 165 and 167 are then closed, valves 174, 182 and 162 are opened, and liquid is pumped into the tubing by the pump P. The valve V being in its upper position fluid in the tubing string below the train of tools may flow into the casing annulus through the ports O and from the annulus through the pipe 161 since the valve 162 is now open. The sensor members 70 and 70a are now held in their inner retracted positions by the engagement of their bosses 90 and 90a with the internal surfaces of the tubing, as shown in FIGURE 1, and, since their bosses are of considerably greater length than any internal recesses of the string of tubing other than the recesses 95 of the locating nipples, the sensor members can move outwardly to their expanded positions only when their bosses move into alignment with a recess 95 of a locating nipple. When this assembly of well tools passes through the uppermost locating nipple 99 connected in the string of tubing and the bosses of the sensor members of the signaling device move into alignment with the latching recess of the uppermost locating nipple, the sensor members 70 and 70a are moved laterally outwardly by their springs 71 and 71a to the positions illustrated in FIGURE 2. This outward movement of the sensor members 70 and 70a moves their shoulders 135 and 135a out of engagement with the shoulders 134 and 134a of the latch lugs 130 and 130a of the latch sleeves 116 and 116a, respectively, and the two latch sleeves are moved inwardly by the springs 119 until their inner edges abut the opposite shoulders 118 and 118a of the mandrel flange.

As the downward movement of the signaling device 20 continues, the cam shoulders 92 of the sensor members 70 and the cam shoulders 91a of the sensor members 70a contact the lower annular shoulder 97 of the locating nipple and, since the latch lugs 130 now prevent inward movement of the sensor members, the sensor members cannot now move further downwardly. The cross pin 84 is now also held against downward movement since it now engages the shoulders 17 defining the lower ends of the slots 85 of the sensor members 70.

The mandrel, the latch sleeves and the upper cross pin 84a are now moved downwardly relative to the sensor members 70 and 70a and to the cross pin 84 against the biasing force exerted by the springs 110 and 111 between the cross pins and against the resistance of the springs 77a of the sensor members 70a. This increased resistance to the movement of the assembly of well tools now offered by the signaling device causes a pressure or shock wave to be generated in the liquid being pumped into the string of tubing which is sensed and recorded by the pressure sensing and recording device 168. Such increase in pressure in the liquid being pumped now causes downward movement of the mandrel, the latch sleeves and of the upper cross piece 84a while the sensor members and the bottom cross pin 84 are held against downward movement until the latch sleeves 116 and 116a move downwardly relative to the sensor members 70 and 70a to positions wherein their latch lugs are out of engagement with the shoulders 141 and 141a of the sensor members 70 and 70a thus releasing the sensor members for inward movement.

The camming engagement between the shoulders 92 of the sensor members 70 and the shoulder 97 of the locating mandrel now causes the sensor members 70 to pivot inwardly above the shoulders 134 of the latch lugs 130 and the camming engagement of their shoulders 135 with the shoulders 134 moves the latch sleeve 116 downwardly on the mandrel. As soon as the shoulders 92 of

the sensor members 70 move out of engagement with the shoulder 97 of the locating nipple, the springs 110 and 111 move the cross pin 84 downwardly on the mandrel until the cross pin 84 again engages the top surface of the inner portion 25 of the ball connector member 22. The engagement of the bottom surface of the cross pin with the surfaces 171 of the sensor members 70 defining the bottom ends of their slots 85 causes simultaneous downward movement of the sensor members 70 with the cross pin 84. The sensor members 70 and the latch sleeve 116 are then again in the positions relative to the mandrel illustrated in FIGURE 1.

When the mandrel and the latch sleeve 116a have moved downwardly relative to the sensor members 70a to the positions wherein the latch bosses 130a are out of engagement with the shoulders or surfaces 141a, the sensor members 70a are pivoted inwardly when their cam shoulders 91a engage the nipple shoulder 97 so that the shoulders 142a of the latch bosses move into engagement with the shoulders 143a of the sensor members 70a. The sensor members 70a will then remain in such upper positions relative to the mandrel and the latch sleeve 116a during the continued downward movement of the signaling device through the string of tubing. The latch bosses will now be lodged in the recesses 145a of the sensor members 70a.

Such pivotal movement of the two pairs of sensor members occurs substantially simultaneously as the train of well tools continues to be moved downwardly through the tubing to the desired location and the signaling device 30 successively passes through the longitudinally spaced locating nipples connected in the tubing. The sensor members move outwardly each time their bosses move into alignment with a latch recess 95 of a locating nipple and cause a shock or pressure wave to travel through the 35 liquid being pumped into the upper end of the tubing when the downward movement of the sensor members 70 is arrested due to their engagement with the lower shoulder 97 of such locating nipple. The pressure sensing and recording device will therefore precisely indicate the 40 location of the train of well tools until the tool T has been located at a desired location in the well tubing.

If it is thereafter desired to move the train of tools upwardly to a higher location in the tubing, the valves 174 and 162 are closed and the valves 165 and 167 are opened. 45 If the pressure of the well is now sufficiently great, it may move the train of tools upwardly. If it is not sufficiently great liquid may be pumped into the annulus A through the pipe 164 and the open valve 165. The liquid pumped into the annulus A passes through the open ports O into the tubing below the train of well tools and moves it upwardly. As the signaling device moves into the lowermost locating nipple it encounters during such upward movement, the sensor members 70 and 70a move outwardly into its latch recess 95 and the upward movement 50 of the sensor members is momentarily arrested when the shoulders 91 of the sensor members 70 and the shoulders 92a of the sensor members 70a engage the upper shoulder 96 of such locating nipple. At this time the upper cross pin 84a engages the shoulders 171a defining the upper ends of the slots 85a of the sensor members 70a and is thus held against further upward movement. The latch sleeve 116a is now in its lowermost position relative to the mandrel while the latch sleeve 116 moves upwardly thereon as soon as the sensor members 70 move outwardly into the internal latch recess 95 and its latch lugs 55 move out of engagement with the shoulders 135 of the sensor member 70 and into engagement with the inner surfaces 141a thereof. When the shoulders 91 of the sensor members 70 engage the upper nipple shoulder 96, the sensor members are held against upward movement 60 during continued upward movement of the mandrel and of the cross pin 84 until the latch lugs 130 move out of engagement with their inner surfaces 141 whereupon the camming engagement of the shoulders 91 with the shoulder 96 pivots them inwardly so that their shoulders

143 engage the shoulders 142 of the latch bosses. The spring 77 now permit such upward movement of the cross pin 84 relative to the sensor member 70. During the continued upward movement of the signaling device, the sensor members 70 will move in and out of their lower positions relative to the mandrel and the latch sleeve 116. The latch lugs 130 will be in the recesses 145 as the signaling device continues its upward movement.

When the shoulders 92a of the sensor members 70a engage the shoulder 96 of such lowermost locating nipple their further upward movement is arrested. The mandrel and the cross pin 84 now move upwardly against the additional force exerted by the springs 110 and 111 thus causing a pressure shock wave to be transmitted through the liquid to the pressure sensing and recording device 168 thus indicating to the operator that the train of tools is at such locating nipple. Upward movement of the mandrel, the cross pin 84 and the latch sleeves relative to the sensor members then moves the latch lugs 130a upwardly and into alignment with the slots 131a of the sensor members 70a whereupon the camming engagement of the shoulders 92a with the upper shoulder 96 of the locating nipple pivots the sensor members 70a inwardly and the camming engagement of their shoulders 135a with the shoulders 134a of the latch lugs causes the upper latch sleeve 116a to be moved upwardly on the mandrel and the sensor members 70a are then back in the positions illustrated in FIGURE 1. As liquid continues to be pumped into the string of tubing and such string of tools is moved upwardly therethrough, each time the signaling device moves into and through a locating recess a pressure shock wave is transmitted to and sensed by the pressure sensing and recording device 168.

It will now be seen that the signaling device 20 will operate to transmit signals through the liquid which is used to move the train of tools through the tubing whether the signaling device is moving upwardly or downwardly through the string of tubing.

It will now further be seen that the signaling device 20 includes two pairs of sensor members, one pair of which functions when the signaling device is moved in one direction through a flow conductor and the other of which functions when the signaling device is moved in the opposite direction through the flow conductor to increase the force necessary to continue the movement of the signaling device each time the signaling device moves through a section of the flow conductor having an internal recess of predetermined width.

It will further be seen that the signaling device includes latch means for each of the pairs of sensor members for latching them against movement from their expanded or outer positions toward their inner retracted positions and that such latch means is rendered inoperative upon a predetermined movement of the signaling device relative to the expanded sensor members when they are held against movement by an obstruction of the flow conductor to permit the signaling device to move past such obstruction.

The signaling device 209 illustrated in FIGURE 8 is substantially similar to the signaling device 20 differing therefrom in different means for resisting the movement of its cross pins 84 and 84a toward one another and, accordingly, the elements of the signaling device 209 have been provided with the same reference numbers as the corresponding elements of the signaling device 20. The signaling device 209 has instead of the springs 110 and 111 a hydraulic assembly for resisting the movement of the cross pins 84 and 84a. The hydraulic assembly provides a greater force resisting movement of one cross pin toward the other than can the springs 110 and 111 whose size is limited due to the relatively small internal diameter of the mandrel 21. The hydraulic assembly includes a tubular member or cylinder 203 having seal assemblies 204 and 205 closing the upper and lower ends of the cylinder. The upper seal assembly includes a tubular body 206 whose external annular flange 207 provides a down-

wardly facing shoulder 208 which limits telescoping inward movement of the tubular body into the cylinder. The tubular body is secured against displacement from the cylinder by a set screw 209 which extends through a suitable aperture in the cylinder into the threaded bore 210 of the tubular body. The inner conical end portion of the set screw 209 engages an annular seat surface 212 of the tubular body to close a filler port 214 thereof through which liquid may be introduced into the cylinder. The tubular body 206 has an external annular recess in which is disposed an O-ring 215 which seals between the cylinder and the tubular body and with an internal annular recess in which is disposed an O-ring 216 which seals between the closure member and the piston rod 217 of a piston 218.

The seal assembly 205 similarly includes a tubular body 219 which is telescoped in the lower end of the cylinder 203 and secured to the cylinder by a set screw 220 which extends through a suitable aperture of the cylinder into the threaded bore 221 of the tubular body 219. The tubular body is provided with an external annular recess in which is disposed an O-ring 223 which seals between the body and the cylinder and with an internal annular recess in which is disposed an O-ring 224 which seals between the body and the piston rod.

The piston 218 includes an annular flange 227 integral with the piston rod and having an external annular recess in which is disposed an O-ring 228 which seals between the piston flange and the cylinder. The piston flange divides the interior of the cylinder into an upper chamber 229 and a lower chamber 230. The piston flange has a vertical flow passage 231 whose lower end opens to a radial slot 232 of the piston flange which opens to the lower chamber. The upper end of the vertical flow passage is closed by a valve ring 234 which abuts the upper annular surface 236 of the piston. The valve ring is biased downwardly against the upper surface of the piston flange to close the upper end of the flow passage by a spring 238 whose lower end engages the upper annular shoulder 239 of the valve ring. The valve ring has internal annular flange 240 which extends upwardly into the lower end portion of the spring 238. The top end of the spring engages the downwardly facing shoulder 242 of a spring retainer ring 243. The retainer ring has a downwardly extending annular flange 244 which telescopes into the upper end of the spring. The retainer ring has a downwardly and inwardly sloping internal surface 246 and is held against upward movement on the piston rod by one or more wedge segments 248 whose inner portions are receivable in an external recess 249 of the piston rod and whose outer surfaces engage the internal surface 246 of the retainer ring.

The piston flange also has a second flow passage 252 whose upper end opens to a radial slot 253 which opens to the upper chamber. The lower end of the passage is closed by a valve ring 254 which abuts the bottom surface of the piston flange and which is biased upwardly towards its closed position by a relatively weak spring 255 whose upper end abuts the bottom surface 257 of the valve ring. The valve ring is preferably provided with a downwardly extending annular spring retainer flange 258. The lower end of spring 255 abuts the spring retainer ring 259 which is similar to the spring retainer ring 243 and is similarly secured to the piston rod by means of wedge segments 260 whose inner portions are received in the annular recess 261 of the piston rod and whose outer upwardly convergent surfaces abut the internal surface of the retainer ring.

It will be apparent that the spring retainer rings may be mounted on the piston rod against longitudinally outward movement thereon by moving them towards the piston flange to positions wherein they permit the wedge segments to be slipped into the recesses and are then moved outwardly on the rod so that the engagement of the conical internal surfaces of the spring retainer rings

with the wedge segments then limits their longitudinal outward movement on the piston rod. Any other suitable means may of course be employed to secure the spring retainer rings to the piston rod.

A bypass or metered orifice passage 265 communicates with the lower chamber through the radial slot 232 and with the passage 252 whose upper end communicates with the upper chamber through the radial slot 253.

The piston is biased upwardly by a spring 268 whose opposite ends engage the top surface of the body 219 and the bottom surface of the piston flange. The upper end of the piston rod engages the bottom surface of the cross pin 84a and the bottom end of the cylinder engages the top surface of the cross pin 84.

The cylinder is filled with an incompressible fluid so that longitudinal movement of the piston rod relative to the cylinder can take place rapidly only when the fluid can flow from one chamber to the other through one or the other of the flow passages 232 and 252 when its valve ring is in open position. A very slow flow of fluid can take place through the orifice 253 and the passage 252 when the valve rings are in closed positions.

In use, if the signaling device is being pumped downwardly through a string of tubing and the bosses of the sensor members 70 move outwardly into the recess of the locating nipple and their downward movement is then stopped by the engagement of the bosses with the lower shoulder 97 of such locating recess, movement of the cross pin 84 is arrested in the manner described in connection with the signaling device 20. Continued downward movement of the mandrel 21 and the cross pin 84a can then be achieved only if the piston 218 moves downwardly relative to the cylinder. Such downward movement of the piston rod is resisted by the pressure of the totally enclosed fluid in the lower portion 230 of the cylinder. This fluid, to pass to the upper portion 229, must rise in pressure sufficiently to lift valve ring 234 away from the piston face 236 and flow through passage 231. This pressure, in turn, is governed by the thrust of spring 238 and the combined areas of two similar ports 231. It is also affected by the rate of movement of the tool string in the tubing controlled by the pumping rate because fluid also flows from the lower to the upper portion of the cylinder through the small fixed orifice 265. At normal and at high pumping rates, the effect of orifice 265 is insignificant but at low rates, it reduces the pressure required to move the piston relative to the cylinder. In this way, control of the pumping rate becomes a means of controlling the amount of resistance to continued movement of the tool string after being temporarily arrested in the recess of the tubing nipple 99. Variation of the thrust of spring 238 also affects the functioning directly. Once the mandrel 21, the cross pin 84a and the latch sleeves on the mandrel have moved downwardly a sufficient distance relative to the sensor members and the cross pin 84 to the position wherein the latch sleeves again permits inward movement of the sensor members, the spring 268 moves the cylinder downwardly relative to the piston, the relatively weak spring 255 permitting the valve ring 254 to move downwardly to open position to permit the flow of the hydraulic liquid through the passage 252 into the lower chamber to permit such downward movement of the cylinder. Downward movement of the cylinder moves the cross pin 84 and the sensor members 70 downwardly relative to the mandrel to their original positions.

If the signaling device is being moved upwardly through the string of tubing and the bosses of the sensor members move outwardly into the recess of a locating nipple, the engagement of the bosses of the sensor members 70a with the upper shoulder nipple then prevent the upward movement of the sensor members 70a and the cross pin 84a. The latch sleeve 116a then prevents pivotal inward movement of the sensor members 70a and further upward movement of the cross pin 84a is arrested. Suf-

ficient pressure must then be developed in the liquid being pumped upwardly through the tubing to cause the mandrel, the cross pin 84 and the latch sleeves to move upwardly relative to the cross pin 84a. This movement can be accomplished only by a displacement of fluid from the lower portion 230 of the cylinder to the upper portion 229 under exactly the same conditions as before described with respect to downward movement of the tool string.

It will thus be apparent that the hydraulic assembly functions in the same manner whether the signaling device is being moved upwardly or downwardly to resist the movement of one pin relative to the other and that since substantially the full force of the spring 238 is exerted through the valve ring across the relatively small area of the passage 231 to resist flow of the fluid therethrough, the increase in the pressure of the liquid moving the signaling device necessary to release the signaling device for continued movement may be made very great.

Referring now particularly to FIGURES 9 through 14 of the drawings, the signaling device 300 includes a central tubular mandrel 301 having a ball connector 302 secured to one end thereof and a socket connector 303 secured to the other end. The ball connector has an inner threaded portion or pin 305 threaded in the lower end portion of the tubular mandrel, an external flange 306 which provides an upwardly facing annular shoulder 307 which limits inward movement of the ball connector relative to the mandrel, a neck portion 308 and a ball 309.

30 to the mandrel, a neck portion 300 and a ball seat 301. The socket connector 303 has a first section 310 threaded on the upper end of the mandrel and having an internal annular flange 312 which provides a spherical seat surface 313 inwardly of the passage 315 of the flange. A spherical seat ring 316 is positioned between the upper annular end shoulder 317 of the mandrel and the downwardly facing internal annular shoulder 318 of the first section 310. The seat section has a spherical seat surface 319 spaced from and facing the seat surface 313 so that the ball of the ball connector may be positioned for limited universal rotation therebetween. The neck of such 40 ball connector would of course then extend upwardly and outwardly through the passage 315 of the socket section. The seat ring may be provided with the annular downwardly extending flange 320 which telescopes into the upper end portion of the mandrel.

45 A protector sleeve 322 is disposed about the mandrel and has an internal annular flange 323 at its lower end which is receivable between the shoulder 307 of the flange 306 of the ball connector and the downwardly facing shoulders 325 of the mandrel. A closure ring 327 substantially closes the space between the mandrel and the upper end of the protector sleeve. The closure ring has a downwardly facing annular recess 328 in which is telescoped the inner upwardly facing flange or reduced portion 329 of the protector sleeve. The sleeve has a pair of longitudinal slots 332 and 333 which extend from the top 50 of the sleeve.

60 of the sleeve. A pair of sensor members 336 have external bosses 338 at their upper ends which are movable outwardly through the slots 333. The sensor members are provided with lower slots 340 whose bottom ends are defined by the upwardly and inwardly convergent surfaces 341 and 342 of the sensor members which provide the pivot edges 343. The pivot edges of the sensor members are received in the downwardly facing recesses 346 of a cross piece 347 which extends through opposed longitudinal slots 348 of the mandrel and into the slots 340 of the sensor members. The upper end portions of the sensor members are biased outwardly toward expanded position by springs 349 whose lower end portions are received in the radially upwardly opening bores 350 and whose upper end portions extend about the shanks of the pivot pins 352 and engage the annular shoulders 354 of the conical heads 355 of the pins. The upper ends of the pivot pins are received in recesses 357 of the sensor members immediately above 75 their slots 340.

The bosses 338 of the sensor members have upper and lower inwardly convergent cam shoulders 360 and 361, respectively. The sensor members below the lower cam shoulders and above their slots 349 have slots 364 whose upper ends are defined by the downwardly facing shoulders 365. The sensor members have internal recesses 368 and upwardly facing downwardly and inwardly extending shoulders 369 and internal shoulders 370.

A tubular latch sleeve 372 is longitudinally movably mounted on the mandrel 301 and has oppositely facing bosses 373 which project outwardly into the slots 364 of the sensor members when the latch sleeve is in the lower position on the mandrel illustrated in FIGURES 9 and 10 of the drawings with the top shoulders 374 of the latch lugs engaging the shoulders 365 of the sensor members. When the latch sleeve is in its upper position on the mandrel, illustrated in FIGURE 11, the outer surfaces 375 of the latch lugs engage the internal shoulders 370 of the sensor members to hold the sensor members in their expanded positions. The upward movement of the latch sleeve on the mandrel is limited by the engagement of its internal upwardly facing shoulders 376 with the downwardly facing annular shoulder 377 of the mandrel. When the mandrel and the latch sleeve are moved upwardly relative to the sensor members from the positions illustrated in FIGURE 11 to positions wherein the internal recesses 368 move into alignment with the latch lugs 373, the sensor members may then again move inwardly toward their retracted positions, the latch lugs then being received in the internal recesses of the sensor members with the upwardly and outwardly extending lower shoulders 378 of the lugs engaging the shoulders 369 of the latch lugs of the sensor members.

The latch sleeve is biased toward its upper position on the mandrel by a pair of springs 380 whose inner portions are received in the longitudinal external recesses 381 of the mandrel and in the longitudinal slots 382 of the latch sleeves. The upper ends of the springs bear against the downwardly facing shoulders 383 of the latch sleeve defining the upper ends of the slots and their lower ends bear against the top surfaces 385 of the spring support blocks 386 which project outwardly from the mandrel through the slots. The inner circular portions 387 of the blocks are received in suitable lateral apertures 388 of the mandrel and are held in place by the protector sleeve 322. Guide pins 390 extend through the springs 380.

The cross pin 347 is biased downwardly in the mandrel toward its lowermost position illustrated in FIGURES 9 and 10, wherein its further downward movement is arrested by the engagement of its bottom surface with the top surface of the pins 305 and the surface of the mandrel defining the lower ends of its slots 348, by a spring 392 whose upper end bears against the seat section 316 of the socket connector 303 and whose lower end bears against the annular upwardly facing shoulder 394 of the cross pin. The cross pin may have an upward spring retainer portion 395 which telescopes into the lower end of the spring.

In use, the signaling device 300 is connected in a train of well tools, such as the train of tools illustrated in FIGURE 7, in place of the tool signaling device 20, which is to be pumped downwardly through a tubing string provided with the locating nipples 99. The signaling device 300 is connected to such train of tools by its connectors 302 and 303. The sensor members 336 are initially positioned in their retracted or inner positions illustrated in FIGURES 9 and 10 when inserted into the string of tubing. When the train of well tools passes through the uppermost locating nipple 99 connected in the string of tubing and the bosses 338 of the sensor members 336 move into alignment with the latching recess 95 of the uppermost locating nipple, the sensor members are pivoted outwardly and their bosses move outwardly into the latching recess. This pivotal outward movement

of the sensor members moves their shoulders 365 out of engagement with the top shoulders 374 of the latch lugs of the latch sleeve. The latch sleeve is thus freed for upward movement on the mandrel and the springs 380 move the latch sleeve upwardly on the mandrel to the position illustrated in FIGURE 11 wherein the outer shoulders or surfaces 375 of the latch lugs engage the shoulders 370 of the sensor members and thus prevent inward movement of the latch lugs. At this time the upward movement of the latch sleeve on the mandrel is limited by the engagement of its upwardly facing internal shoulders 376 with the downwardly facing annular shoulder 377 of the mandrel.

As the downward movement of the train of well tools continues, the bottom cam shoulders 361 of the sensor members engage the lower upwardly facing shoulder 97 of the locating nipple which then prevents further downward movement of the sensor members and of the cross piece since the sensor member cannot pivot inwardly. Further downward movement of the train of well tools can then be accomplished only by a sufficient increase in the pressure of the liquid which is moving the train of well tools downwardly to overcome the additional force exerted by the spring 392 and move the mandrel and the latch sleeve downwardly relative to the cross piece and the sensor members. The pressure or shock wave generated in the liquid when the downward movement of the sensor members is arrested is sensed and recorded by a suitable device in the manner described in connection with the signaling device 20. The mandrel and the latch sleeve move downwardly relative to the sensor members and the cross piece until the shoulders 375 of the latch sleeve are moved out of engagement with the shoulders 370 of the sensor members whereupon the camming engagement of the lower cam shoulders 361 of the bosses of the sensor members with the lower shoulder 97 of the locating recess pivots the sensor members inwardly and the shoulders 365 of the sensor members again move into engagement with the top shoulders 374 of the sensor members. The force of the spring 392 is then effective to move the cross piece 347, the sensor members and the latch sleeve downwardly on the mandrel back to their lower positions illustrated in FIGURES 9 and 10. This sequence of operation of the signaling device 300 occurs each time the signaling device passes downwardly through a locating nipple 99 of the tubing string.

Upward movement of the train of well tools having the signaling device 300 will not result in the production or generation of such pressure and shock waves in the liquid being pumped into the string of tubing below such train of well tools to move it upwardly. When the signaling device moves upwardly into the first locating recess it reaches during the upward movement of the train of well tools its sensor members will pivot outwardly when their bosses move into alignment with the recess 95 and the latch sleeve will be moved upwardly by the springs 380 to the positions illustrated in FIGURE 11. As the upward movement of the train of well tools continues the upper cam shoulders 360 of the sensor members engage the upper shoulder 96 of the locating nipple and thus their upward movement is arrested. The upward movement of the mandrel, the cross pin and the latch sleeve, however, will continue against the resistance of the springs 349 which bias the sensor members outwardly and upwardly. The latch sleeve will move upwardly with the mandrel since it is biased to its upper position by its springs 380. When the latch lug shoulders 375 move out of engagement with the shoulders 370 of the sensor members, the camming engagement of the cam shoulders 360 with the nipple shoulder 96 pivots the sensor members inwardly and their shoulders 369 are moved into engagement with the lower shoulders 378 of the latch lugs 373, the outermost portions of the latch lugs being received in the internal recesses 368 of the sensor members. The sensor members will then remain in this lower position

relative to the latch sleeve and the latch sleeve will then remain in its upper position on the mandrel during the continued upward movement of the string of well tools through the string of tubing. Since the springs 349 are relatively weak no appreciable increase in pressure of the pumped liquid is required to cause upward movement of the signaling device through the locating nipples.

It will be apparent that the signaling device 300, when connected in a train of well tools and moved through a string of tubing provided with the locating nipples with its ball connector 302 in its lowermost position, will generate or produce the shock and pressure waves in the liquid moving the train of well tools downwardly through such string of tubing. If it is desired that the location of the train of well tools be precisely known both during its downward and upward movement through the string of tubing, the train of well tools would be provided with two of the signaling devices 300, one of them being connected in the train of tools in the position illustrated in FIGURES 9 and 10, the other being connected in the string of well tools in vertically reversed position by suitable connecting means so that one such signaling device would produce pressure and shock waves during downward movement of the train of tools through the flow conductor and the other would produce the pressure and shock waves in the liquid during its upward movement of the train of tools through the string of tubing.

It will now be seen that each of the described and illustrated forms of the signaling device embodying the invention includes a mandrel having a pair of sensor members mounted for limited longitudinal movement thereon and for laterally outward movement relative thereto, a latch sleeve movably mounted on the mandrel and biased for movement to its latching position wherein the latch sleeve holds the sensor members, when they move to their expanded position, against movement to their retracted positions, and means for resisting movement of the mandrel and the latch sleeve relative to the sensor members, when the sensor members are in their extended positions and held against movement, in the flow conductor, as by their engagement with an internal annular shoulder of a flow conductor, to positions wherein the latch is out of latching engagement with the expanded sensor members.

It will further be seen that the sensor members are biased toward positions where they will be engaged by the latch sleeve when it moves to its latching position in the well tools 20 and 200 by the spring 77 and in the well tool 300 by the similar springs 349 which bias the sensor members laterally outwardly.

Referring now particularly to FIGURES 15 through 27 of the drawing, the signaling device 400 embodying the invention includes a tubular main body or mandrel 401 and sensor and control assemblies 402 and 403, respectively, mounted on the mandrel. A top socket connector assembly 405 is rigidly secured to the upper end of the mandrel. The socket connector assembly has an internal annular flange 406 into which is threaded the upper end portion of the mandrel and an internal annular flange 407 which provides an annular arcuate seat surface 408 which is spaced above the similar seat surface 409 of a seat ring 410 threaded in the flange 406 above the top end of the mandrel. The ball of a ball connector assembly, such as the ball 411 of a ball connector assembly 412 shown mounted on the lower end of the mandrel, may be positioned for limited universal rotation. A spring retainer nut 413 is threaded in the upper end of the mandrel for reasons to be described below. The top connector member and spring retainer nut are held against rotation relative to the mandrel and each other by a pin 413a which extends through aligned apertures thereof.

The ball connector assembly 412 is mounted on the lower end of the main mandrel by means of a screw 414 whose head provides an annular top shoulder 414 which engages the downwardly facing shoulder 415 of the upper internal annular flange 416 of the upper sec-

tion 417 of the ball connector assembly. The lower section 418 of the ball connector assembly is threaded on the upper section and has a dependent neck 419 with which the ball 411 is integral. The signaling device may be connected in a train of tools by similar connector assemblies. For example, a lower well tool of a train of tools is connectable to the bottom connector assembly, and thus to the mandrel, by a socket connector assembly on the upper end of the lower well tool which receives the ball 411 of the signaling device and an upper well tool is connectable to the top connector assembly by a ball connector assembly on the lower end of the upper tool whose ball is positioned between the seat surfaces 408 and 409 of the top connector assembly.

The sensor assembly 402 includes a substantially tubular cage 425 longitudinally slidable on an intermediate portion of the mandrel and a pair of sensor members 428 and 428a pivotally mounted on the cage. The cage includes a pair of upper and lower flange portions 432 and 433, spaced vertical side portions 434 and 435, and horizontal planar brace portions 436 and 437 which extend between the side portions. The cage may be machined from a single piece of work stock so that its various portions are integral with one another, or, if desired for ease of manufacture, the vertical side portion 435 and the brace portions may be formed of separate pieces which may be welded to the other portions of the cage as illustrated in FIGURE 22. The cage has been shown in views other than FIGURE 22 as being formed of a single piece for clarity of illustration. The vertical side portion 434 has a horizontal outwardly extending flange portion 438. The top flange member 432 and the flange portion 438 are provided with pairs of aligned apertures 444 and 445, respectively, which are aligned with one another and with a pair of upwardly opening bores 446 in the bottom flange portion 433. Pivot pins or posts 448 and 448a extend through the apertures 444 and 445 and into the bores 446 and are rigidly secured by pins 451 which extend through suitable aligned apertures in the upper ends of the pins and in the upper flange portion 432. The sensor member 428 has horizontal top and bottom arms 461 and 462 which are positioned between the upper and lower flange portions 432 and 433 of the cage and arms 463 and 464 which are positioned above and below the middle flange portion 438 of the cage. The arms of the sensor member 428 are provided with vertical apertures 465 which are aligned with the apertures of the flange portions of the cage and through which the pivot pin 448 extends whereby the sensor member 428 is pivotally movable about the vertical axis of the pin. The sensor member 428 is biased in a counterclockwise direction, FIGURE 18, by a pair of springs 467 and 468 disposed about the pin, the spring 467 being disposed between the arms 461 and 463 and the spring 468 being disposed between the arms 464 and 462. The lower end portion of the spring 467 is secured to the sensor member as by insertion into a bore thereof and its upper end portion engages one edge of the vertical frame portion 434. The lower spring 468 has its lower end portion similarly secured to the sensor member and its upper end portion engages the opposite edge of the portion 434. The springs 467 and 468 are prestressed during the installation of the sensor member 428 on the cage 425 and thus bias the sensor member 428 outwardly in a counter-clockwise direction, FIGURE 18. The lateral outward pivotal movement of the sensor members is limited by the engagement of the inner surfaces of their arms with the vertical portion 434 of the mandrel.

The sensor member 428a is of similar structure to the sensor member 428 and similarly mounted on the cage and biased outwardly in a clockwise direction about the axis of the pin 448a, as seen in FIGURE 18, and, accordingly, elements of the sensor member 428a and its mounting and biasing means have been provided with the same reference numerals, to which the subscript *a*

has been added, as the corresponding elements of the sensor member 428 and its mounting and biasing means.

The sensor members 428 and 428a are provided with a pair of internal horizontal upper and lower bosses 470, 471, 470a and 471a, respectively, whose function will be described below.

The cage 428 is vertically movably mounted on an intermediate portion of the mandrel which has a vertical side 475, vertical sides 478 and 479 which extend perpendicularly from opposite edges of the side 475, and planar vertical surfaces 480 and 481 which extend convergently inwardly from the edges of the sides 478 and 479 to a central vertical planar surface 482 which lies parallel with the side 475.

The vertical portion 434 of the cage has a configuration corresponding to the configuration of the vertical surfaces 480, 482 and 481 of the mandrel so that the cage is vertically slidably but non-rotatably mounted on the intermediate portion of the mandrel with its vertical portion 434 being engageable with the mandrel vertical surfaces 480, 481 and 482 and its vertical portion 435 being engageable with mandrel side 475.

The side 478 of the intermediate portion of the mandrel is provided with an upper pair of spaced horizontal recesses 491 and 492 in which is receivable the upper boss 470 of the sensor member 428 and with a pair of lower horizontal recesses 493 and 494 in which is receivable the lower boss 471. The side 479 is provided with similar recesses 491a, 492a, 493a and 494a in which are receivable the bosses 470a and 471a of the sensor member 428a. The recesses of the mandrel sides 478 and 479 open through the side surfaces 480 and 481, respectively, and through the side 475 and increase progressively in depth from the side surfaces 480 and 481 to the side 475 in order to accommodate the sensor member bosses whose widths increase progressively outwardly from their arms. The sensor members are movable inwardly to retracted positions when the cage, and therefore the sensor members, is in an upper or lower position on the mandrel. The sensor members are held locked in expanded positions when the cage is in an intermediate position due to the engagement of the bosses 470 and 471 of the sensor member 428 with the locking surfaces 496 and 497 of the side 478 between the upper and lower pairs of recesses and the engagement of the bosses 470a and 471a of the sensor member 428a with the locking surfaces 496a and 497a of the side 479 between its pairs of recesses.

The cage 425 of the sensor assembly is biased to its intermediate position on the mandrel, illustrated in FIGURES 15 and 16, by a pair of centering springs 501 which are disposed in the vertical passages 502 of the vertical cage portion 435. Each of the springs 501 has an upper portion disposed about a reduced lower end portion 504 of an upper pin 505 which extends downwardly into its passage 502. The upper ends of the springs bear against the downwardly facing annular shoulders 507 of the upper pins. The lower portions of the springs are disposed about the upper reduced end portions 510 of lower pins 511 which extend upwardly into the passages 502. The lower ends of the springs bear against the upwardly facing annular shoulders 512 of the lower pins. Longitudinal movement of the upper pins relative to the cage is limited by pins 514 which are secured to the cage and extend through the passages 502 and external longitudinal recesses 515 of the upper pins. Similarly longitudinal movement of the lower pins 511 is limited by pins 517 secured to the cage which extend through the passages 502 and external longitudinal recesses 518 of the lower pins. The upper pins engage the annular bottom shoulder or end surface 520 of the top connector member 405 while the enlarged bottom portions or heads 522 of each lower pin 511 engage the upwardly facing shoulder 523 of the mandrel and the top shoulder 524 of a latch housing 525 mounted on the mandrel.

The latch housing 525 of the control assembly 403 is biased upwardly to its uppermost position on the mandrel, 75

FIGURE 15, by a spring 528 whose upper end portion is received in an annular downwardly opening recess 529 and bears against the annular shoulder 530 defining the upper end of the recess. The lower portion of the spring is disposed about the upper section of the bottom connector assembly and its lower end bears against the annular upwardly facing shoulder 532 thereof. The housing has a bottom internal annular flange 534 whose top annular end surface 535 is engageable with the downwardly facing shoulder 536 of the mandrel to limit upward movement of the housing on the mandrel.

The housing is held against rotation by a pin 537 which passes through aligned apertures in the housing, the mandrel and the screw 414.

15 A control sleeve 540 is disposed about the mandrel and in the housing. The control sleeve is held against downward movement by a plurality of circumferentially spaced pins 541 whose lower ends bear against the top end surface 542 of the upper section of the bottom connector assembly. The pins extend upwardly through vertical apertures or passages 543 in the bottom flange 534 of the housing. All of the pins, such as the pin 541a, except a single pin 541b, are short and their upper ends bear against the bottom surface of the control sleeve. The long pin 541b extends into, and is press fitted in, a downwardly opening bore 545 of the control sleeve and thus is rigid therewith to limit rotation of the control sleeve in the housing. Since the passages 543 are of somewhat larger diameter than the pins 541 and since only one of the pins, 20 the pin 541b, is rigidly secured to the control sleeve, the pins and the control sleeve are free to move vertically but not to rotate.

25 The control sleeve is releasably held in either its inoperative lower position, illustrated in FIGURE 15, or its operative upper position in the latch housing by detent assemblies 550 carried in horizontal parallel bores 551 of the control sleeve. Each of the detent assemblies includes a pair of latch balls 552 and a spring 553 disposed therebetween which biases the balls outwardly from opposite ends of the bores 551. The outer portions of the balls are 30 receivable in the lower and upper annular internal latch recesses 555 and 556 of the latch housing. The upper and lower ends of each latch recess are defined by outwardly convergent annular internal shoulders of the latch housing. The top shoulder defining the upper end of the lower latch recess will cam the latch balls inwardly into the bores 551 against the resistance of the springs 553 when a predetermined axial force is exerted on the control sleeve.

35 When the control sleeve 540 is in the lower position shown in FIGURE 15 and the detent balls 552 are biased outwardly into the lower housing recess 555 by the springs 553, the upper ends of the pins touch the bottom of the control sleeve and their lower ends touch the top shoulder 542 of the ball connector assembly 412.

40 The relative upward movement of the assembly 412 against the spring 528 is limited so that the pins 541 slide through apertures in the housing flange 534 and push the control sleeve upwardly to shift the balls from the lower recess 555 to the upper recess 556. The balls then hold the sleeve firmly in that position.

45 The latch housing is provided with lateral apertures 558 through which a suitable tool may be inserted in the external recesses 559 of the control sleeve to move the control sleeve back to its lower position in the housing.

50 The control sleeve is provided with a pair of opposed upwardly opening slots 560 and 561 narrowed at their lower portions to cause the control sleeve to have downwardly and inwardly sloping cam shoulders 562 and vertical locking surfaces 563 which are engageable with the cam bosses 564 of a trigger link 565 to cause the trigger link to be pivoted in a counter-clockwise direction, FIGURE 15, about the horizontal axis of the pins 570 by means of which the upper end of the trigger link is pivotally connected to the cage, to its inoperative position

and then locked therein upon upward movement of the control sleeve in the latch housing to its upper operative position.

The trigger link 565 comprises a pair of substantially vertical legs 571 and 572 which are connected at their upper end portions by a connector portion 572. The upper end portion of the leg 571 is received between a pair of parallel dependent legs 574 of the cage 425 and is pivotally secured thereto by a pivot pin 570 which extends through suitable aligned apertures in the legs. Similarly, the upper end portion of the leg 572 of the trigger link extends between the dependent pair of spaced legs 576 of the cage and is pivotally connected thereto by a pivot pin 570. The pivot pins are provided with enlarged heads which limit their inward movement due to their engagement with the outer surface of the trigger link legs and are held against outward movement by split lock rings 580 whose outer portions are received in internal annular recesses 581 of the outer legs 574 and 576. The lower end portions of the trigger link legs are provided with aligned slots 583 in which are received the outer end portions of a transverse trigger plate 585 which extends between the legs and through the aligned vertical slots 586 of the mandrel. The plate is secured to the legs by a pair of pins 587 which extend through suitable aligned apertures in the trigger plate and in the trigger link legs. The trigger plate has an upwardly opening middle slot 590 which provides an upwardly facing planar horizontal catch surface 591 which is adapted to engage the downwardly facing shoulder 592 of a catch or sear plate 593 disposed in a lateral recess 594 of a control rod 595 slidably disposed in the longitudinal bore 596 of the mandrel. The trigger plate on either side of the slot 590 has upwardly facing cam shoulders 597 which are engageable with the upwardly and inwardly sloping cam surfaces 598 of the mandrel at the slots 586 thereof.

The trigger link is biased in a counter-clockwise direction about the axis of its pivot pins 570 by a spring 600 whose lower end portion is received in an upwardly opening bore 601 of the connector portion 573 of the trigger link. The upper end of the spring extends into a downwardly opening bore in the bottom of the lower flange 433 of the cage. The lower enlarged portion 605 of the control rod, which is provided with the recess 594 is disposed in the lower enlarged portion 606 of the bore 596 of the mandrel and has above the recess a vertical planar surface 607 which is engaged by a pin 608 secured to the mandrel and extending through the enlarged bore portion 606 to prevent rotation of the control rod.

The control rod is biased upwardly by a spring 610 whose upper portion extends about the reduced bottom end portion 611 of the control rod and whose upper end bears against the downwardly facing annular shoulder 612 of the control rod. A lower portion of the spring extends about the reduced upper portion 614 of the screw or nut 413 and its lower end bears against the upwardly facing shoulder 615 thereof.

The top end of the control rod is engaged by the bottom end of a dependent rod 620 of a cross pin 621. The cross pin extends through the aligned longitudinal slots 622 of the mandrel. The cross pin is biased downwardly relative to the mandrel by an outer spring 625 disposed about the mandrel and in the top connector assembly below the internal flange 406. The top end of the outer spring bears against the downwardly facing annular shoulder 626 of the flange 406 while its lower end bears against the outer top surfaces 627 of the cross pin. The cross pin is also biased downwardly relative to the mandrel by an inner spring 628, disposed in the mandrel, whose lower portion extends about the upwardly extending pin 630 of the cross pin and its lower end engages the inner top surfaces 631 of the cross pin. The upper portion of the spring is disposed about a downwardly extending pin 633 of the nut 413 and its upper end bears against the downwardly facing annular shoulder 634 of the nut.

In use, the signaling device 400 is connected in a train of tools such as the string of tools illustrated in FIGURE 7 which includes two or more sealing well tools such as the well tools 171 and 172 which sealingly engage the internal surfaces of the tubing to close the passage thereof. Such sealing tools may be connected in the train above as well as below the signaling device. The external bosses 640 and 640a of the sensor members 428 are considerably longer than any internal recess of the string of tubing other than the recesses 95 of the locating nipples 99 and are substantially shorter than the recesses 95. The bosses have outwardly convergent top and bottom shoulders 641 and 642. The control sleeve 540 is positioned in its lower inoperative position wherein it is held by the detent assemblies 550.

The train of tools is then inserted into the string of tubing in the same manner described in connection with the tool 20 and, as the tool 400 is inserted into the lubricator, the mandrel 401 is moved downwardly relative to the sensor members 428 and 428a against the resistance of the centering springs 501 to align their inner bosses 470, 470a, 471 and 471a with the upper recesses 491, 491a, 493 and 493a of the mandrel and the sensor members are then pivoted inwardly to their retracted positions 25 against the resistance of the springs which bias them outwardly about the vertical axes of the pins 448 and 448a. The trigger link is pivoted in a clockwise direction prior to the movement of the cage to its upper position in order that the force of the springs 625 and 628 be ineffective to 30 resist this movement. The catch edge 591 of the trigger link plate is now above the sear plate edge 592 and the trigger link is held in an outer inoperative engagement by the engagement of the cam shoulders or edges 597 of its link plate with the vertical surfaces 643 of the mandrel 35 defining upper portions of the sides of the mandrel slots above the cam shoulders 598. The sensor members are then held in their inner retracted positions by the engagement of their bosses with the internal surfaces of the tubing. Since the bosses of the sensor members are of 40 appreciably greater length than any internal recess of the string of tubing other than the recesses 95 of the locating nipples, the sensor members can move outwardly to their expanded positions only when their bosses move into alignment with a recess 95 of a locating nipple. The train of tools is then moved downwardly by fluid pumped into 45 the tubing at the surface in the manner described above and when the train of well tools passes through the uppermost locating nipple 99 connected in the string of tubing and the bosses of the sensor members of the signaling device move into alignment with the latching recess of this uppermost locating nipple, the sensor members 428 and 428a are moved laterally outwardly by the springs disposed about the pins 448 and 448a. As soon as the bosses move out of the upper recesses of the pair of mandrel 50 recesses, the centering springs 501 move the cage and therefore the sensor members downwardly relative to the mandrel and the tubing to the position illustrated in FIGURE 16 wherein the inner bosses engage the locking surfaces 496, 497, 496a and 497a of the sides 478 and 479 of the mandrel so that the sensors are then held against 55 inward movement. This downward movement of the cage relative to the mandrel occurs prior to the engagement of the bottom shoulders 642 and 642a of the sensor members with the annular shoulder 97 of the locating nipple, the length of the nipple recess 96 being appreciably greater than that of the bosses to permit this downward movement of the sensor members in the nipple recess and relative to the mandrel while the downward movement of the train of tools and of the mandrel through the tubing continues. 60 This downward movement of the cage and therefore of the trigger link, relative to the mandrel and the control rod now causes the edges 597 of the trigger link plate to move downwardly and below the mandrel cam shoulders 598 and the trigger link is pivoted to its operative position 65 illustrated in FIGURES 15 and 16.

Continued downward movement of the train of tools and downward movement of the signaling device 490 then causes the bottom shoulders 642 and 642a of the sensor members to engage the bottom upwardly facing shoulder 97 of the locating nipple 99 and further downward movement of the sensor members, and therefore of the cage and the trigger link, is arrested. As the downward movement of the mandrel and the control rod continues, the edge 592 of the sear plate 593 engages the edge 586 of the trigger link plate whereupon further downward movement of the control rod is arrested. Further downward movement of the mandrel then continues against the resistance of the outer and inner springs 625 and 628 since the control rod is now held against downward movement and in turn holds the cross pin 621 against further downward movement. The increased resistance to the downward movement of the mandrel, and therefore to the downward movement of the train of tools due to the force of the springs 625 and 628 requires an increase of several hundred pounds in the force moving the train of tools downwardly in order that the downward movement continue. The resultant pressure rise in the liquid above the train is virtually instantaneous since the liquid has negligible compressibility and a steep fronted "pressure" or "shock" wave is generated and travels upwardly through the liquid and is detected and recorded by the device 168. As the mandrel moves downwardly relative to the control rod before the lock surfaces of the sides 478 and 479 of the mandrel move out of engagement with the sensor member bosses, the shoulders or edges 597 of the trigger plate are engaged by the cam shoulders 598 of the mandrel and the trigger link is pivoted in a clockwise direction, FIGURE 15, to move the edge 591 of the trigger link plate out of engagement with the edge 592 of the sear plate. The control rod is now suddenly released for downward movement and is moved downwardly relative to the mandrel by the springs 635 and 639 which are then rendered ineffective to resist further downward movement of the mandrel. The downward movement of the mandrel is now accelerated and as the upper recesses of the pairs of recesses now move into alignment with the internal bosses of the sensor members, the camming engagement of the shoulders 642 and 642a of the sensor members with the bottom shoulder 97 of the locating nipple pivots the sensor members inwardly and the sensor members move out of the locating nipple and continue to move downwardly with the mandrel.

This sequence of operation of the signaling device is repeated each time the signaling device passes through a locating recess until downward movement of the train of tools is arrested due to the engagement of the lowermost tool of the train with an internal obstruction, such as a stop 645 of FIGURE 7 located in the lower portion of the tubing at such locations that at least one or more of the sealing tools of the train are positioned above the valve so that fluid under pressure pumped into the lower end of the tubing through the port O will cause upward movement of the train. The downward movement of the tools of the train below and connected to the bottom connector assembly 412 of the signaling device, and therefore of the bottom connector assembly 412 and the control sleeve 540, is arrested while the downward movement of the mandrel 401, the cage 425 which is now held against movement relative to the mandrel since the sensor members are in their retracted positions with their bosses in the upper groove of recesses of the mandrel, and the trigger link which is connected to the cage, as well as the tools of the train above the mandrel, continues against the resistance of the spring 528 until the spring is compressed and all movement of the device is arrested. The pressure rise in the liquid above the train caused by this arrest of movement is detected by the device 168. This downward movement of the trigger link relative to the control sleeve causes the bosses 564 of the trigger link which is in its inoperative position to move into align-

ment with the surfaces 563 of the control sleeve which thereafter hold the trigger link against movement to its operative position. The control sleeve is latched in its upper position by its detent assemblies when the balls thereof move into the upper latch recess 556 of the latch housing. Fluid under pressure then introduced into the string of tubing through the ports O will then cause the train of tools to move upwardly through the tubing. As the signaling device 490 moves into the lowermost locating nipple during such upward movement, the sensor members move outwardly into its recess 95 and the centering springs then move the cage to its intermediate position wherein the sensor members are again locked against movement toward their retracted position. As the upward movement of the signaling device continues, the top shoulders 641 and 641a of the bosses of the sensor members engage the top shoulder 96 defining the upper end of the locating nipple. As the upward movement of the sensor members and the cage is thus arrested while the mandrel continues to move upwardly in the tubing and relative to the sensor members, the control rod moves therewith since the trigger link is now held in its inoperative position by the control sleeve. As the mandrel continues to move upwardly, the recesses 492, 494 and 492a and 494a of the mandrel move into alignment with the inner bosses of the sensor members and the camming engagement of the top shoulders 641 and 641a of the bosses with the locating nipple shoulder 96 cams the sensor members into their retracted positions as the cage and the sensor member assume their lower positions in the mandrel and the cage then moves upwardly with the mandrel. As the train of tools continues to move upwardly through the string of tubing, the sensor members move outwardly into the recess 95 of each locating nipple through which the signaling device passes and then are again cammed inwardly in the manner described above. Since the trigger link is held in its inoperative position, the springs 625 and 628 offer no resistance to the upward movement of the mandrel when the sensor members move outwardly into a locating nipple recess and then arrest upward movement of the cage and only a slight increase in the resistance to the movement of signaling device through such locating nipple occurs due to the force of the springs 467, 467a, 468 and 468a resisting inward movement of the sensor members and the force of the centering springs resisting upward movement of the mandrel relative to the cage.

After the control sleeve has been moved to its upper inoperative position, the trigger link is held thereby in its inoperative position. If after the train of tools has been moved upwardly in the tubing is then again moved downwardly by liquid being pumped into the upper end of the tubing, the downward movement of the signaling device through the locating nipples during such subsequent downward movement will not cause great pressure or shock waves since the increased resistance to the movement of the train of tools offered by the signaling device each time it passes through a locating nipple will be only that offered by the springs which bias the sensor members outwardly and by the centering springs 501 as the mandrel moves downwardly relative to the cage after the sensor members have moved outwardly into the locating nipple recess and have engaged the bottom shoulder 97 of the locating nipple.

After the train of tools has been pumped downwardly through the tubing a predetermined distance and prior to the engagement of the lowermost tool of the train of tools with the stop 645 in the lower end of the string of tubing, the train may be moved first upwardly therein and then downwardly and provide the signal pressure and shock waves during such subsequent downward movement. During such initial upward movement of the train of tools, which may be caused by pumping liquid into the annulus and thence into the string of tubing through the ports O, as the signaling device moves into the first locating nipple it encounters during such upward movement, the sensor members move outwardly into the nipple re-

cess 95 and the cage and the sensor members move outwardly into the nipple recess 95 and the cage and the sensor members are then moved downwardly by the force of the centering springs to their intermediate positions on the mandrel and the trigger link is pivoted by the spring 600 back to its operative position. As the upward movement of the train of tools continues, the top shoulders 641 and 641a of the sensor members engage the top annular shoulder 96 of the locating nipple and further upward movement of the sensor members and the cage is arrested while upward movement of the mandrel continues. The springs 625 and 628 do not resist such continued upward movement of the mandrel relative to the cage since the control rod is not secured to the cross pin 621. The trigger link plate 585 does not at any time engage the shoulder 646 defining the lower end of the lateral recess 594 of the enlarged bottom portion 605 of the control rod 595 since the lower mandrel recesses 492a, 494a, 492 and 494 move into alignment with the internal bosses of the sensor members before such engagement can take place. The force moving the train of tools and the mandrel upwardly increases to the degree necessary to overcome the force of the springs which resist the inward movement of the sensor members and of the centering springs which resist upward movement of the mandrel relative to the cage until the sensor members are cammed inwardly to their retracted positions with their bosses in the lower recesses of each pair of recesses of the mandrel. Thereafter upon movement of the signaling device through progressively higher locating nipples above such lowermost nipple, as the sensor members move into alignment with the internal recess of each higher locating nipple, they move outwardly thereinto and the cage is moved upwardly on the mandrel by the centering springs to its intermediate position and as the top shoulders 641 and 642a of the sensor member engage the top internal shoulders of the locating nipple recesses, the mandrel again moves upwardly relative to the cage and the sensor members, and the sensor members again are cammed inwardly to their retracted positions as the lower recesses of the pair of mandrel recesses move into alignment with their internal bosses. During subsequent downward movement of the train of tools in the tubing, as the signaling device moves through the first locating nipple it reaches during such subsequent downward movement, the sensor members again move outwardly into the recess of such locating nipple and the cage is moved upwardly by the centering springs to its intermediate position on the mandrel. When the downward movement of the cage is arrested due to the engagement of the bottom shoulders 462 and 462a of the sensor member bosses with the bottom shoulder 97 of such locating nipple, the springs 625 and 628 again resist downward movement of the mandrel relative to the cage until the mandrel moves downwardly relative to the cage and the trigger link plate edges 597 are engaged by the cam shoulders 598 of the mandrel and the trigger link is pivoted to cause its plate to move out of engagement with the sear plate. The further downward movement of the mandrel then moves it to a position wherein the upper recesses of the pairs of mandrel recesses move into alignment with the corresponding inner bosses of the sensor members to permit inward movement of the sensor members and the sensor members are moved to their inner retracted positions. Thereafter as the downward movement of the train continues, the cage and the sensor members are moved downwardly relative to the mandrel by the centering springs 501 as the sensor members move into alignment with and outwardly into the recesses of succeeding locating nipples. The mandrel moves downwardly relative to the cage and the sensor member against the resistance of the springs 625 and 628 when the downward movement of the sensor members is arrested due to their engagement with the bottom nipple shoulder 97 until the upper recesses of the pairs of mandrel recesses again move into alignment with the internal

bosses of the sensor members and the sensor members are again moved to their retracted positions in the manner previously described and produce pressure or shock waves of relatively great intensity in the liquid moving the train of tools through the tubing.

The trigger link is pivoted to its inoperative position before the locking surfaces 496, 496a, 497 and 497a of the mandrel move out of engagement with the internal bosses of the sensor members to release the sensor members for movement to their retracted positions upon a predetermined longitudinal movement of the mandrel in either direction relative to the cage and the sensor members, when the movement of the cage and the sensor members is prevented by the engagement of the sensor members with the top or bottom shoulders 96 or 97 of the locating nipple, to cause the mandrel to move very rapidly relative to the sensor members and its locking surfaces to move out of engagement with the internal bosses of the sensor members thus precluding release of one sensor member for movement to its retracted position prior to such release of the other sensor member even if the two sensor members when held against movement by engagement with an internal shoulder of the locating nipple are not perfectly longitudinally aligned relative to each other due to imperfections in the dimensions of the sensor members, the mandrel or the locating nipples caused either during their manufacture or by wear. It will be appreciated that the extent to which the sensors, cage, link, and control rod have to move, before getting relieved of the heavy load of springs 625, 628, is terminated by the disengagement of the trigger face 591 from the sear face 592 by the action of the cam shoulders 598 of the mandrel against the edges 597 of the plate 585. It should also be noted that this occurs before the inner bosses of a sensor move out of engagement with the mandrel which they engage. It will thus be seen that the triggered release of the heavy spring load occurs at one single centralized point and not at more than one point such as would be necessary if triggering occurred at four "simultaneous" surfaces of contact of the sensor members with the mandrel such as 470 and 496, 471 and 497, 470a and 496a and 497a and 497a; or at two "simultaneous" surfaces of contact of the sensor member with the nipples such as 641 and 96, and 641a and 96. This avoids the manufacturing difficulty of ensuring that a plurality of trigger edges function simultaneously and precluding uneven stresses involved if one trigger edge releases before the others.

The signaling device 400 is preferred over the signaling devices 20, 200 and 300 for the reason that the placement of the resisting springs 625 and 628 at a location remote from the sensor members instead of within the mandrel as is the case of the signaling devices 20, 200 and 300, permits the mandrel 401 of the signaling device 400 to be of greater thickness so that the additional resistance provided by the signaling device each time it passes through a locating nipple may be increased without damage to the mandrel due to collapse thereof by the radially inward forces exerted thereon by the sensor members due to the camming engagement of the shoulders of the external bosses of the sensor members with the nipple shoulders 96 or 97. As a result the springs 625 and 628 may be chosen to provide a relatively greater force resisting movement of the mandrel relative to the cage and the sensor member and therefore pressure or shock waves in the pumped liquid of relatively great intensity which are of course more easily detected by the detector and recording device 628.

If it is desired that the signaling device 400 during its initial downward movement through the tubing not transmit pressure shock waves each time the signaling device moves through a locating nipple but do so only after the train of tools in which it is connected has first been moved downwardly in the tubing to a lowermost location wherein the lowermost tool of the train engages the stop 645 and then upwardly in the tubing, the control

sleeve 540a, FIGURE 28, is substituted for the control sleeve 540 in the latch housing 525. The control sleeve 540a is substantially similar to the control sleeve 540 and, accordingly, elements of the control sleeve 540a have been provided with the same reference numerals to which the subscript *a* has been added, as the corresponding elements of the control sleeve 540. The control sleeve 540a is initially placed in its lowermost position in the latch housing 525 wherein the balls 552 of its detent assembly 550 extend into the lower latch recess 555 and its locking surfaces 563a are in engagement with the bosses 564 of the trigger link and hold the trigger link in its inoperative position. As a result, during initial downward movement of the train of tools, the signaling device does not cause shock and pressure signal waves to be produced in the liquid moving the train of tools downwardly through the tubing as the signaling device moves through the locating nipples. When the lowermost tool of the train of tools engages the stop 645 of the tubing, the control sleeve 540a is moved upwardly in the latch housing to its inoperative position wherein the latch balls of its latch assemblies move into the upper latch recess 556 and the trigger link bosses 564 are below the cam surfaces 562a of the control sleeve. The trigger link is then free to move inwardly to its operative position wherein the edge 591 of its plate 585 is engageable with the edge 592 of the sear plate. The train of tools is then moved upwardly by liquid pumped into the annulus and thence into the tubing through the ports O. The signaling device moves upwardly through the locating nipples without causing pressure or shock signal waves in the liquid being pumped as explained above. During subsequent downward movement of the train the signaling device movement will generate or cause pressure and shock signal waves in the liquid being pumped into the tubing and moving the train of tools downwardly as explained above since the trigger link is now not held in its inoperative position by the control sleeve 540a.

Referring now particularly to FIGURES 29 through 40 of the drawings, the signaling device 700 is a preferred embodiment of the invention providing maximum flexibility of operation since it may be adjusted to produce pressure signals in the pumped liquid selectively during only downward, only upward, or both downward and upward movement of the signaling device through a string of tubing having the locating nipples 99 connected thereto. The signaling device 700 includes a tubular mandrel 701 on which are mounted a sensor assembly 702 and a control assembly 703. The top socket connector assembly 703a of the signaling device secured to the upper end of the mandrel includes an upper section 704 threaded on the external annular flange 705 of the mandrel and secured against rotation therefrom by a suitable pin 706 which extends through aligned apertures in the upper section and the mandrel. The upper connector section has an internal annular flange 707 which provides a downwardly facing annular spherical seat surface 708. The top socket connector assembly also includes a seat ring 709 threaded in the top connector section which provides an upwardly facing annular spherical seat surface 710. A bottom ball connector assembly 712 is mounted on the lower end of the mandrel by means of a screw 413 whose head provides an annular top shoulder 714 which engages the downwardly facing shoulder 715 of the internal annular flange 716 of the upper section 717 of the bottom connector assembly. The lower section 718 of the assembly is threaded on the upper section and has a dependent neck 720 provided with a ball 721. The ball 721 is positionable in a socket connector assembly, such as the socket connector assembly 703, of a lower tool of a train and, similarly, the ball of a ball connector assembly of an upper tool of the train is positionable in the socket connector assembly 703 whereby the mandrel is connectable to such upper and lower tools and is movable relative thereto at the locations of its connections thereto.

The sensor assembly 703 includes a cage substantially identical in structure to the cage 425 of the signaling device 400 and longitudinally slidable on an intermediate portion of the mandrel, and a pair of sensor members 728 and 728a which are substantially identical to the sensor members of the signaling device 400. The cage includes a pair of upper and lower flange portions 732 and 733, spaced vertical side portions 734 and 735, and horizontal planar brace portions 736 and 737 which extend between the vertical side portions. The vertical side portion 734 has a horizontal outwardly extending flange portion 738. The top flange portion 732 and the flange portion 738 are provided with pairs of aligned apertures 744 and 745, respectively, which are aligned with one another and with a pair of upwardly opening bores 746 of the lower flange portion. Pivot pins or posts 448 and 448a extend through the apertures 444 and 445 and into the bores 446 and are rigidly secured against rotation by pins 451 which extend through suitable aligned apertures in the upper ends of the pins and the upper flange portion 432.

The sensor member 728 has horizontal top and bottom arms 761 and 762 which are positioned and adjacent the upper and lower flanges 732 and 733, respectively, of the cage and arms 763 and 764 which are positioned above and below the middle flange portion 738 of the cage. The arms of the sensor member 728 are provided with vertical apertures 767 which are aligned with the apertures of the flange portions of the cage through which the pivot pin 728 extends whereby the sensor member 728 is pivotally movable about the vertical axis of the pin. The sensor member is biased in a counter-clockwise direction, FIGURE 30, by a pair of springs 767 and 768 disposed about the pin, the spring 767 being disposed between the arms 761 and 763 and the spring 468 being disposed between the arms 764 and 762. The upper end portion of the spring 767 engages one edge surface of the vertical cage portion 734 and its other end is received in a bore of the sensor member 728. The lower spring 768 similarly has its upper end portion engaging a side of the vertical cage portion 734 and its lower end portion is positioned in a bore of the sensor member 728.

The sensor member has a pair of internal horizontal upper and lower bosses 770 and 771 whose function will be described below.

The sensor member 728a is similar in structure to the sensor member 728 and is similarly mounted on the cage and biased outwardly in a clockwise direction about the axis of the pin 748a as seen in FIGURE 36, and, accordingly, elements of the sensor member 728a and its mounting and biasing means are provided with the same reference numerals, to which the subscript *a* has been added, as the corresponding elements of the sensor member 728 and its mounting and biasing means.

The cage 725 is vertically movably mounted on an intermediate portion of the mandrel which has a vertical side 775, vertical sides 778 and 779 which extend perpendicularly from opposite edges of the side 475, and planar vertical surfaces 780 and 781 which extend convergently outwardly from the edges of the sides 778 and 779 to a central vertical planar surface 782 which lies parallel to the side 475. The vertical portion 734 of the cage has a configuration corresponding to the configuration of the vertical surfaces 780, 781 and 782 of the mandrel so that the cage is vertically slidably but non-rotatably mounted on the intermediate portion of the mandrel between the planar internal surface of the vertical portion 435 is engageable with the mandrel side 475 and the vertical internal surfaces of the vertical cage portion 734 being engageable with the mandrel surfaces 480, 481 and 482.

The vertical planar side 778 of the intermediate portion of the mandrel is provided with an upper pair of spaced horizontal recesses 791 and 792 in which is receivable the upper internal boss 770 of the sensor mem-

ber 728 and with a lower pair of horizontal recesses 793 and 794 in which is receivable the lower internal boss 471. The vertical planar mandrel side 779 is provided with a similar upper pair of recesses 791a, 792a and a lower pair of recesses 793a and 794a in which are receivable the upper and lower bosses 470a and 471a, respectively, of the sensor member 782a. Sensor members are movable inwardly to retracted positions when the cage, and therefore the sensor members are in an upper or lower position on the mandrel. The sensor members are held locked in expanded positions when the cage is in an intermediate position on the mandrel due to the engagement of the bosses 770 and 771 of the sensor member 728 with the locking surfaces 796 and 797 of the mandrel side 778 between the upper and lower pairs of recesses and the engagement of the bosses 770a and 771a of the sensor members 728a with the locking surfaces 796a and 797a of the mandrel side 779 between its pairs of recesses.

The cage 725 of the sensor assembly is biased to its intermediate position by a pair of centering springs 891 which are disposed in the vertical passages 892 of the cage vertical portion 735. Each of the springs has an upper portion disposed about the reduced lower end portion 804 of an upper pin 895 which extends downwardly into its passage 802. The upper ends of the springs bear against the downwardly facing annular shoulders 867 of the upper pins. The lower portions of the springs 891 are disposed about the upper reduced end portions 810 of lower pins 811 which extend upwardly into the passages 802. The lower ends of the springs bear against the upwardly facing annular shoulder 812 of the lower pins. Longitudinal movement of the upper pins relative to the cage is limited by pins 814 which are secured to the cage and extend through the passages 802 and longitudinal slots 815 of the upper pins. Similarly, longitudinal movement of the lower pins 811 is limited by pins 817 secured to the cage which extend through the passages 802 and longitudinal slots 818 of the lower pins. The upper pins engage the bottom end surface of a spring retainer ring 820 mounted on the mandrel above the cage. Downward movement of the spring retainer ring on the mandrel is limited by the engagement of its bottom surface with the upwardly facing shoulder 821 of the mandrel at the top ends of its planar sides 775, 778 and 779. The lower ends of the pins 811 are rigidly secured as by welding to a foot plate 824. Downward movement of the foot plate 824 relative to the mandrel is limited by the engagement of the bottom surface of the foot plate with the upwardly facing external shoulder 825 of the mandrel at the lower end of its vertical planar side 775. The springs 891 tend to hold the cage in the intermediate position on the mandrel illustrated in FIGURES 29 and 34 wherein the internal bosses of the sensor members are in expanded positions and locked against inward pivotal movement to their retracted positions by the engagement of their internal bosses with the locking surfaces of the mandrel.

The control assembly 763 includes a control sleeve assembly 830 mounted on the mandrel. The control sleeve assembly includes a collet ring 831 having a plurality of resilient upwardly extending collet fingers 832 provided at their upper ends with radially inwardly extending lugs 833 which are selectively receivable in the bottom, middle and top external annular recesses 835, 836 and 837 of the mandrel for releasably latching the control assembly in a bottom, middle or top position on the mandrel. The inner ends of the collet lugs have inwardly convergent upper and lower cam shoulders 843 and 844 and the shoulders of the mandrel defining the top and bottom sides of each latch recess are outwardly convergent whereby the camming engagement of the lug shoulders 843 with the downwardly facing shoulders defining the upper end of the bottom and middle latch

recesses moves the collet fingers resiliently outwardly to permit upward movement of the control sleeve assembly from its bottom position to its middle position and from its middle position to its top position. Similarly, the camming engagement of the bottom lug shoulders 844 with the shoulders of the mandrel defining the lower ends of the top and middle latch recesses moves the collet fingers outwardly to permit downward movement of the control sleeve assembly from its top position to its middle position and from its middle position to its bottom position. The control sleeve assembly includes a pair of sleeve sections 851 and 852 disposed in the collet ring and rigidly secured thereto by welding. The control sleeve section 852 is provided with recesses 854 in its vertical sides between upper and lower locking surfaces 856 and 857 provided by its vertical sides. The top and bottom ends of the recesses are defined by the outwardly convergent upper and lower cam shoulders 860 and 861, respectively, which are engageable with the cam bosses 864 of a trigger link 865 to cause the trigger link to be pivoted in a counter-clockwise direction, FIGURE 29, about the horizontal axis of the pins 870 by means of which the upper end of the trigger link is pivotally connected to the cage, to its inoperative position upon movement of the control assembly from its middle position illustrated in FIGURE 30 to either its top or bottom position. The engagement of the cam bosses 864 of the trigger link with the upper locking surfaces 856 of the control sleeve section 852 holds the trigger link in its inoperative position when the control sleeve assembly is in its bottom position on the mandrel and their engagement with the lower locking surfaces 857 of the control sleeve section 852 holds the trigger link in its inoperative position when the control assembly is in its top position on the mandrel. The sleeve section 851 cooperates with the control sleeve section 852 to help hold the control sleeve assembly in properly centered position on the mandrel.

Downward movement of the control sleeve assembly 40 on the mandrel is limited by a plurality of circumferentially spaced pins 871 whose lower ends bear against the top end surface 872 of the upper section 717 of the ball connector assembly 712. The outer portions of the pins are disposed in vertical internal circumferentially spaced recesses 873 of the horizontal flange 844 of a 45 spring retainer ring 875 disposed on the mandrel and their inner portions are disposed in vertical external recesses 876 of the mandrel which are aligned with the recesses 843. All of the pins such as the pin 871a, except 50 a single pin 871b, are short and their upper ends bear against the bottom surface of the control section 851 or 852. The upper end portion of the long pin 871b extends into and is press fitted in an internal recess 877 so that it is rigid with the control sleeve assembly and thus 55 prevents rotation of the control sleeve assembly relative to the mandrel.

Since the passages 873 are of somewhat larger diameter than the pins 871 and since only one of the pins 871b is rigidly secured to the control sleeve, vertical movement 60 between the control assembly and the housing may take place while rotation of the control sleeve is prevented.

Upward movement of the spring retainer ring 875 on the mandrel is limited by the engagement of its flange 874 with the downwardly facing shoulder 880 of the 65 mandrel. The spring retainer ring 875 is rigidly secured to the mandrel by a pin 876a which extends through aligned apertures of the ring and the mandrel and a slot 877a of the screw 713. The ball connector assembly 712 is yieldably biased downwardly by a spring 882 whose upper portion extends into the spring retainer ring with its top end bearing against the bottom surface of its flange 874 and whose lower portion extends about the upper section 717 of the ball connector assembly with its bottom end bearing against the upwardly facing annular shoulder 75 886 of the upper connector section. Upward movement

of the ball connector assembly, and therefore of the pins 871 on the mandrel is limited by the engagement of the top end surface 872 of the upper connector section 717 with the annular bottom end surface 838 of the mandrel.

The trigger link 865 comprises a pair of substantially vertical legs 891 and 892 which are connected at their upper ends by a connector portion 893. The upper end portion of the leg 891 is received between a pair of parallel dependent legs 894 of the cage 725 and is pivotally secured thereto by a pivot pin 870 which extends through suitable aligned apertures in the legs. Similarly, the upper end portion of the leg 892 extends upwardly between the dependent pair of spaced legs 895 of the cage and is pivotally connected thereto by a pivot pin 870. The pivot pins are provided with enlarged heads which limit inward movement of the pins due to their engagement with the outer surfaces of the trigger link legs. The pins are held against outward movement by split lock rings 896 whose outer portions are received in internal annular recesses 897 of the outer legs 894 and 895.

The lower end portions of the trigger link legs have aligned vertical slots 899 in which are received the outer end portions of a vertical trigger plate 900 which extends between the legs and through aligned vertical slots 902 of the mandrel. The trigger plate is secured to the legs by a pair of pins 904 which extend through suitable aligned apertures in the trigger plate and in the trigger link legs. The trigger plate has an upwardly opening upper slot 905 which provides an upwardly facing planar horizontal catch surface 908 which is adapted to engage the downwardly facing edge or shoulder 909 of an upper catch or sear plate 912 disposed in a lateral recess 914 of the lower enlarged section 915 of a control rod 916. The lower enlarged section of the control rod is threaded on the lower end of the stem 918 of the control rod. The trigger plate on either side of its upper slot 906 has upwardly facing cam shoulders 920 which are engageable with the upwardly and inwardly sloping upper cam surfaces 922 of the mandrel at the slots 902 thereof. The trigger plate also has a downwardly opening lower slot 925 which provides a downwardly facing planar horizontal catch surface 925 which is adapted to engage the upwardly facing horizontal shoulder 928 of a lower catch or sear plate 925 disposed in the lateral recess 914 of the control rod. The trigger on either side of the lower slot 925 has downwardly facing cam shoulders 930 which are engageable with the downwardly and inwardly sloping lower cam surfaces 931 of the mandrel at the slots 902 thereof. The upper and lower sear plates are rigidly secured to the large bottom section of the control rod, as by welding, and are spaced from one another so that the middle portion of the trigger plate may be disposed therebetween with the top and bottom edges 908 and 925 thereof in position to the bottom shoulder 909 of the upper sear plate and the top shoulder 928 of the lower sear plate.

The trigger link is biased in a counter-clockwise direction, FIGURE 29, about the axis of its pivot pins 870 toward its operative position wherein the shoulders 908 and 925 are between and in position to engage the shoulders 909 and 928 respectively of the sear plates by three springs 935 whose lower end portions are disposed in upwardly opening bores 936 of the connector portion 893 of the trigger link and whose upper end portions are disposed downwardly opening bores in the bottom of the lower flange portion 733 of the cage.

The lower enlarged section 915 of the control rod is disposed in the lower enlarged portion 940 of the longitudinal bore 941 of the mandrel. The stem of the control rod adjacent its upper end has an upper longitudinal slot 950 which is aligned with longitudinal slots 951 of the mandrel and a cross pin 952, rigidly secured to a top spring retainer ring 954, extends through the upper control rod slot 950 and the upper mandrel slots 951. The top retainer ring is biased upwardly on the mandrel by an

outer spring 957 whose top end bears against the bottom surface of the annular external flange 953 of the top retainer ring and whose bottom end bears against the top surface of the bottom spring retainer ring 820. The stem of the control rod also has a longitudinal slot 960 which is aligned with the lower longitudinal slot 961 of the mandrel and a cross pin 964 extends through the control rod slot 960 and the mandrel slots 961. The cross pin 964 is biased downwardly and away from the top spring retainer ring 954 by an inner spring 966 whose top end bears against the bottom annular shoulder 968 of the top spring retainer ring and whose bottom end bears against top surface of a middle spring retainer ring 969 which in turn bears against the end portions of the lower cross pin which extends outwardly of the mandrel slot 961.

It will now be apparent that the outer and inner springs yieldably hold the control rod in its intermediate position illustrated in FIGURES 29 and 30 since the upper cross pin is held in engagement with the downwardly facing surface 971 of the control rod stem defining the upper end of the stop slot 950 and the lower pin is held in engagement with the upwardly facing surface 972 of the control rod defining the lower end of the lower slot 960. The sear plates when the control rod is in its intermediate position are in position to receive the trigger link plate therebetween when the trigger link is pivoted in a counterclockwise direction.

If it is desired that the signaling device 700, which is connectable in a train of tools in the same manner as the signaling device 440 and is movable through a string of tubing, FIGURE 7, by liquid pumped into the string of tubing above or below the train of tools, provide a relatively small increased resistance to the movement of the train each time it moves downwardly through a locating nipple and a relatively great increasing resistance to upward movement through the locating nipples, and that the signaling device be rendered inoperative when it is moved to a lowermost position in the string of tubing wherein the lowermost tool of the train engages the stop 645 in the lower end of the tubing, the control sleeve assembly is positioned in its middle position on the mandrel wherein the collet finger lugs 833 are disposed in the middle latch recess 841 and the pins 871 are of such length that their lower ends engage the shoulder 872 of the upper section 717 of the ball connector assembly 712 as illustrated in FIGURES 29 and 30 and will move the control sleeve assembly to its top position on the mandrel when the mandrel moves downwardly relative to the ball connector assembly 712 and its bottom end shoulder 880 engages the top end shoulder 872 of the ball connector assembly.

The external bosses 990 and 990a of the sensor members are longer than any internal recess of the string of tubing other than the recesses 95 of the locating nipples 99 and are substantially shorter than the recesses 95. The bosses 990 and 990a have outwardly convergent top and bottom shoulders 991, 992, 991a and 992a. The train of tools is inserted into the string of tubing in the same manner as described in connection with the signaling device 20. As the signaling device 700 is inserted into the lubricator, the mandrel is moved downwardly relative to the cage and the sensor members against the resistance of the centering springs 801 to align the internal sensor member bosses 770, 770a, 771 and 771a with the recesses 791, 791a, 793 and 793a, respectively, of the mandrel. The sensor members are then pivoted inwardly to their retracted position against the resistance of the springs which bias them outwardly. The trigger link is pivoted in a clockwise direction prior to the movement of the cage to its inoperative position in order that the force of the springs 957 and 966 be ineffective to resist this movement. The catch edge or shoulder 908 of the trigger link plate is now above the edge 909 of the upper sear plate 912 and the trigger link is held in its outer inoperative position by the engagement of the cam shoulders or edges 920 of

its plate with the vertical surfaces 993 defining upper portions of the sides of the mandrel slots 992 above the upper cam shoulders 922. The sensor members are then held in their inner retracted positions by the engagement of their external bosses with the internal surfaces of the tubing. Since the bosses of the sensor members are considerably greater in length than any internal recess of the string of tubing other than the recesses 95 of the locating nipples, the sensor members can move outwardly to their expanded positions only when their bosses move into alignment with a recess of a locating nipple. The train of tools is then moved downwardly by liquid pumped into the tubing above the train of tools. When the signaling device reaches the uppermost locating nipple connected in the string of tubing, and the sensor members of the signaling device move into alignment with the recess of such uppermost locating nipple, the sensor members are moved laterally outwardly by the springs 767, 767a, 768 and 768a. As soon as the internal bosses of the sensor members move out of the upper recesses of the pairs of mandrel recesses, the centering springs 801 move the cage, and therefore the sensor members and the trigger link downwardly relative to the mandrel and the control rod to the position illustrated in FIGURES 29 and 34. This downward movement of the cage relative to the mandrel occurs prior to the engagement of the bottom shoulders 992 and 992a of the sensor members with the bottom annular shoulder 97 of the locating nipple, the length of the nipple recess 95 being considerably greater than that of the external bosses of the sensor members to permit this downward movement of the sensor members relative to the mandrel and the nipple while the downward movement of the train of tools and of the mandrel through the tubing continues. The inner bosses then engage the locking surfaces between each pair of recesses so that the sensors are then held against movement to their retracted positions. The downward movement of the trigger link relative to the mandrel and the control rod causes the cam shoulders 920 of the trigger link plate to move downwardly and below the mandrel cam shoulders 922 and the trigger link is pivoted by the springs 935 to its operative position illustrated in FIGURES 29 and 30 wherein its plate 900 is disposed between the sear plates of the control rod. Continued downward movement of the signaling device then causes the bottom shoulders 992 and 992a of the sensor members to engage the bottom shoulder 97 of the locating nipple and further downward movement of the sensor members, and therefore of the cage and the trigger link is arrested. As the downward movement of the mandrel and the control rod continues, the bottom edge 909 of the upper sear plate 912 engages the top edge 908 of the trigger link plate whereupon downward movement of the control rod is arrested. The lower cross pin 964 is also held against downward movement since it engages the surface 972 of the control rod defining the lower end of the slot 950 thereof and the lower cross pin in turn holds the lower retainer ring against downward movement. As the mandrel continues to move downwardly, the upper cross pin 952 moves downwardly therewith since it is secured to the top retainer ring 958 which in turn is engaged by the bottom annular shoulder of the top external flange 705 of the mandrel and the annular bottom end shoulder of the socket connector section 704. Downward movement of the mandrel therefore is now resisted by the centering springs 801 and the inner spring 966 which is compressed between the upper and lower retainer rings. The outer spring 957 is not compressed since the bottom spring retainer ring 820 is free to move downwardly with the mandrel. The resistance to the movement of the mandrel, and therefore to the train of tools in which it is connected, offered by the inner spring 966 and the center springs now causes pressure and shock waves to be transmitted through the liquid being pumped into the tubing.

As the mandrel continues to move downwardly, before the mandrel lock surfaces 795, 796a, 797 and 797a move

out of engagement with the inner sensor member bosses 779, 770a, 771 and 771a, the cam shoulders or edges 920 of the trigger plate are engaged by the cam shoulders 922 of the mandrel and the trigger link is pivoted in a clockwise direction, FIGURE 29, to its inoperative position and the top edge 908 of its plate 900 is moved out of engagement with the bottom edge 909 of the upper sear plate 912. The control rod is thus released suddenly for downward movement relative to the mandrel and is moved downwardly by the force of the spring 966. The downward movement of the mandrel relative to the cage and the sensor members is now accelerated and, as the upper recesses of the pairs of mandrel recesses now move into alignment with the internal bosses of the sensor members, the camming engagement of the bottom shoulders 992 and 992a of the sensor members with the bottom shoulder 97 of the locating nipple pivots the sensor members inwardly, the sensor members move out of the locating nipple recess and the cage and the sensor members then continue to move downwardly with the mandrel. This sequence of operation of the signaling device is repeated each time the signaling device passes downwardly through a locating recess.

Prior to the engagement of the lowermost tool of the train with the internal stop 645 of the tubing, the train of tools may be moved upwardly by reversing the circulation of the pump fluid, that is, by pumping the liquid into the annulus and through the ports of the tubing into the tubing below the train of tools. As the train of tools moves upwardly and the signaling device moves into the first locating nipple it encounters during such upward movement, the sensor members are moved outwardly into its recess 95, the centering springs move the cage to its intermediate position on the mandrel wherein the sensor members are again locked against movement toward their retracted positions, and the trigger link is moved to its operative position. As the upward movement of the signaling device continues, the top shoulders 991 and 991a of the sensor members engage the top internal shoulder 96 of the locating nipple.

When the upward movement of the sensor members and the cage is thus arrested and the upward movement of the mandrel continues, the top edge 923 of the lower sear plate 929 engages the bottom catch edge 926 of the trigger link plate and upward movement of the control rod is now arrested. Continued upward movement of the mandrel due to the engagement of the bottom spring retainer ring 820 by the mandrel shoulder 821 and the lower cross pin 964 causes the bottom retainer ring and the lower cross pin to move upwardly with the mandrel and relative to the control rod. The upper cross pin 952, and therefore the top spring retainer ring 954, is now held against upward movement due to the engagement of the upper cross pin with the surface 971 of the control rod stem defining the upper end of the upper slot 950. The upward movement of the mandrel and therefore of the train of tools is now resisted by the combined force of the two springs 957 and 956, as well as of the centering spring, pressure and shock waves of relatively great intensity are generated in the liquid by the relatively high pressure that is required to continue the upward movement of the train of tools. As the mandrel moves upwardly relative to the cage and the control rod, before the lock surfaces of the mandrel move out of engagement with the inner sensor member bosses, the lower cam shoulders 931 of the mandrel at the slots 992 thereof engage the trigger link plate lower cam shoulder 930 and the trigger link is pivoted in a clockwise direction to move the lower edge 926 of its plate 900 of engagement with the edge of the lower sear plate 929. The control rod is thus suddenly released for upward movement and is moved upwardly by the force of the springs 957 and 956. The upward movement of the mandrel continues and, as the lower recesses of the pairs of recesses of the mandrel move into alignment with the internal bosses of the sen-

sor members, the camming engagement of the top shoulders 991 and 991a of the sensor members with the top shoulder 96 of the locating nipple pivots the sensor members inwardly and the sensor members move out of the locating nipple recess and move upwardly with the mandrel. This sequence of operation of the signalling device is repeated each time the signalling device passes through a locating recess.

When the downward movement of the tools below the bottom ball connector assembly 712 of the signalling device is arrested due to the engagement of the lowermost tool with the tubing stop 645, the downward movement of the ball connector assembly and the control sleeve assembly is also arrested. The downward movement of the mandrel 701, the cage 425 which is now held against movement relative to the mandrel since the sensor members are in their retracted positions with their inner bosses in the upper grooves of the pair of mandrel recesses of the mandrel, the trigger link and the tools of the train above the mandrel continues against the resistance of the spring 882. This downward movement of the trigger link relative to the control sleeve brings its bosses 864 into alignment with the lower locking surfaces 857 of the control sleeve section 852 and thereafter the trigger link is held by the locking surfaces 857 against movement towards its operative position. During such downward movement of the mandrel relative to the control sleeve assembly, the collet finger lugs are moved outwardly from the middle latch recess 836 and then move into the top latch recess 837 when the downward movement of the mandrel is arrested due to the engagement of its bottom end shoulder 835 with the shoulder 872 of the upper ball connector section 717. When the train of tools is then moved upwardly through the string of tubing, the signalling device during its movement through the locating nipples does not appreciably increase the resistance to the upward movement of the train of tools since the control rod will move with the mandrel at all times even though as the signalling device moves through the locating nipples, the sensor members pivot outwardly into their recesses and the cage is momentarily held against upward movement as the sensor members engage the top shoulders 396 of the locating nipples. Once the control sleeve assembly is in its top position subsequent upward or downward movement of the train of tools will not be resisted by the force of the springs 957 and 966 since the trigger link will be held in its inoperative position.

If it is desired that the signal device be inoperative during initial downward movement of the train of tools through the tubing and be rendered operative only when the lowermost tool of the train engages the stop 645 of the tubing, the pins 871 are of shorter length than the pins illustrated in FIGURE 30 and of such length that the short ones of these pins corresponding to the pins 871a of FIGURE 30, engage the bottom surfaces of the control sleeve sections 851 and 852 and the shoulder 872 of the ball connector assembly when the control sleeve assembly is in its lowermost position on the mandrel with the collet finger lugs 833 disposed in the bottom latch recess 835. When the control sleeve assembly is in this bottom position its lock surfaces 856 engage the bosses 864 of the trigger link and hold the trigger link in its inoperative position. When the lowermost tool of the train engages the stop 645, the downward movement of the mandrel and the cage relative to the bottom connector assembly 712, the pins 871 and the control sleeve assembly continues until the bottom of the mandrel engage the shoulder 872 of the ball connector assembly. This causes the control sleeve assembly to again assume its middle position, wherein the collet finger lugs are disposed in the middle latch recess and the trigger link bosses 864 are in alignment with the recesses 854 of the control sleeve section 852. The trigger link may thereafter pivot in a counterclockwise direction to move its plate between the sear plates whenever the cage moves to its intermediate position on the mandrel.

Once the control sleeve assembly has been moved to its middle position it will remain in its middle position and the signalling device will function in the manner described above during either upward or downward movement through the string of tubing and the locating nipples. It will be apparent, of course, that if such short pins 871 are used and it is desired that the signalling device operate even during the initial downward movement through the tubing, the control sleeve assembly is initially placed in its middle position on the mandrel before the signalling device is inserted into the tubing.

Referring now particularly to FIGURE 41 if it is desired that the signalling device offer a greater resistance during its downward movement through a locating recess than during its upward movement therethrough, the middle ring 969a is rigidly secured to or is made integral with the middle ring 820a while a ring 958a is movable with respect to the ring 954a. In this case, when the downward movement of the control rod is arrested due to engagement of the trigger link plate with the upper sear plate, downward movement of the mandrel relative to the control rod cause compression of both the outer spring 957 and the inner spring 966 since both the middle ring 969a and the bottom ring 820a will now be held against downward movement by the lower cross pin 964 while the upper top retainer ring 958a and the ring 954a will move downwardly with the mandrel and the upper cross pin. During upward movement of the signalling device through a locating nipple, when the control rod is held against upward movement due to the engagement of the trigger link plate with the lower sear plate while upward movement of the mandrel continues, only the inner spring 966 will be compressed since the upper cross pin 952 now will hold only the retainer ring 954a against upward movement, the ring 958a being movable upwardly with the mandrel. It will thus be apparent that the resistance offered by the signalling device during its upward movement through a locating nipple will be smaller than during its downward movement.

It will be apparent that if desired the middle ring 969 of the signalling device 700 may be rigidly secured to its bottom ring 820 in which case both springs 957 and 956 will be operative during both the downward and the upward movement of the signalling device through a locating nipple and the increase in the resistance to the movement of the signalling device will be the same whether it is moving upwardly or downwardly therethrough.

It will now be apparent that the signalling device affords great flexibility in the modes of operation thereof permitting the increase in the resistance to its movement through the locating nipples to be the same whether moving upwardly or downwardly therethrough, to be greater if it is moving in one direction than the other, to be inoperative when moving in one direction or the other, and to be rendered either operative or inoperative upon the movement thereof to a lowermost position in a string of tubing having an obstruction, such as the stop 645 therein.

It will further be seen that if the lower sear plate of the signalling device 710 is removed, the signalling device will be operative only during its downward movement through the tubing and that if the upper sear plate is removed it will be operative only during its upward movement through the tubing.

The foregoing description of the invention is explanatory only, and changes in the details of the construction illustrated may be made by those skilled in the art, within the scope of the appended claims, without departing from the spirit of the invention.

What is claimed and desired to be secured by Letters Patent is:

1. A signalling device movable through a flow conductor having a plurality of longitudinally spaced internal recesses each providing a pair of longitudinally spaced annular facing shoulders, said signalling device including:

a mandrel; first and second sensor means mounted on said mandrel for limited longitudinal movement relative thereto, said sensor means being movable laterally relative to said mandrel between an inner retracted position and an outer expanded position; means operatively associated with said first and second sensor means yieldably resisting longitudinal movement of said first sensor means in one direction relative to said mandrel and of said second sensor means in a second direction opposite to said one direction relative to said mandrel; means biasing said sensor means toward said expanded position; first latch means operatively associated with said first sensor means and movable into latching engagement with said first sensor means when said signaling device is being moved through said flow conductor when said first sensor means moves outwardly to its expanded position into an annular recess of said flow conductor for preventing inward movement of said first sensor means from its expanded to its retracted position to prevent movement of said first sensor means through said flow conductor when said first sensor means engages one of the longitudinally spaced annular shoulders provided by the annular recess in which it is disposed, said first latch means being moved out of latching engagement with said first sensor means upon movement of said mandrel in said one direction relative to said first sensor means against the force exerted by said means resisting longitudinal movement of said sensor means whereby an increase in the force moving said signaling device in said flow conductor is required to permit movement of said first sensor means to its retracted position and permit movement of said signaling device through flow conductor, said first latch means moving out of latching engagement with said first sensor means upon movement of said mandrel in said second direction relative to said first sensor means when said first sensor means engages the other of the longitudinally spaced annular shoulders provided by the annular recess; and second latch means operatively associated with said second sensor means and movable into latching engagement with said second sensor means when said signaling device is being moved through said flow conductor in said second direction and said second sensor means moves outwardly to its expanded position and into an annular recess of said flow conductor for preventing inward movement of said second sensor means from its expanded to its retracted position to prevent movement of said second sensor means through said flow conductor when said second sensor means engages said other of the longitudinal spaced annular shoulders provided by the annular recess in which it is disposed, said second latch means being moved out of latching engagement with said second sensor means upon movement of said mandrel in said second direction relative to said first sensor means against the force exerted by said means resisting longitudinal movement of said sensor means whereby an increase in the force moving said signaling device in said flow conductor is required to permit movement of said second sensor means to its retracted position and movement of said signaling device through said flow conductor, said second latch means moving out of latching engagement with said second sensor means upon movement of said mandrel in said first direction relative to said first sensor means when said second sensor means engages said one of the longitudinally spaced annular shoulders provided by the annular recess.

2. The signaling device of claim 1; and means biasing said first sensor means longitudinally in said one direction and said second sensor means longitudinally in said second direction relative to said mandrel for yieldably holding said sensor means in position to be engaged by said latch means.

3. A signaling device movable through a flow conductor having a plurality of longitudinally spaced internal recesses each providing a pair of longitudinally spaced annular facing shoulders, said signaling device including: a mandrel; sensor means mounted on said mandrel for

limited longitudinal movement relative thereto; said sensor means being movable laterally relative to said mandrel between an inner retracted position and an outer expanded position; means operatively associated with said sensor means yieldably resisting longitudinal movement in one direction of said sensor means relative to said mandrel; means biasing said sensor means toward expanded position; and latch means operatively associated with said sensor means and movable into latching engagement with said sensor means when said signaling device is being moved through said flow conductor and said sensor means move outwardly to its expanded position into an annular recess of a flow conductor for preventing inward movement of said sensor means from its expanded to its retracted position and prevent movement of said first sensor means through the flow conductor when said sensor means engages one of the longitudinally spaced annular shoulders provided by the annular recess in which it is disposed, said latch means being moved out of latching engagement with said sensor means upon movement of said mandrel in said one direction relative to said sensor means against the force exerted by said means resisting movement of said sensor means whereby the increase in the force moving said signaling device in said flow conductor is required to permit movement of said sensor means to its retracted position and permit movement of said signaling device through the flow conductor, said latch means moving out of latching engagement with said sensor means upon movement of said mandrel in a second direction opposite said first direction relative to said sensor means when said sensor means engages the other of the longitudinally spaced annular shoulders provided by an annular recess of the flow conductor in which it is disposed during movement of said signaling device through said flow conductor.

4. The signaling device of claim 2 wherein said means resisting movement of said sensor means comprises a hydraulic cylinder and a pair of cross pins on opposite ends of said cylinder, one of said cross pins engaging one of said first sensor means and the other of said cross pins engaging the other of said second sensor means, said hydraulic cylinder having plunger means biased outwardly from opposite ends thereof and engaging said cross pins, and valve means in said cylinder dividing said cylinder into two chambers and restricting fluid flow between the two cylinders.

5. The signaling device of claim 2 wherein said means resisting longitudinal movement of said sensor means comprises a spring disposed in said mandrel, a first transverse cross pin engaging said first sensor means and a second transverse cross pin engaging said second sensor means, said spring biasing said cross pins away from one another.

6. A signaling device including: an elongate mandrel; sensor means mounted on said mandrel for limited longitudinal movement relative thereto, said sensor means being movable laterally relative to said mandrel between an inner retracted position and an outer expanded position; means biasing said sensor means toward said expanded position; means for yieldably resisting movement of said mandrel in one longitudinal direction relative to said sensor means; and means on said mandrel and said sensor means engageable to lock said sensor means in said expanded position when said sensor means is in said expanded position, said last mentioned means releasing said sensor means for movement to retracted position upon predetermined longitudinal movement of said mandrel relative to said sensor means against the resistance of said means yieldably resisting movement of said mandrel in said one direction.

7. A signaling device including: an elongate mandrel; a cage mounted on said mandrel for limited longitudinal movement relative thereto; sensor means mounted on said mandrel for movement relative to said cage and said mandrel between an inner retracted position and an outer expanded position; means biasing said sensor means to-

ward said expanded position; means for yieldably resisting movement of said mandrel in one longitudinal direction relative to said cage; lock means on said mandrel and said sensor means engageable when said sensor means is in said expanded position for locking said sensor means in said expanded position; and trigger means operatively associated with said resisting means and said cage and in operative position when said sensor means is in expanded position for causing said resisting means to resist longitudinal movement of said mandrel in said one direction when said sensor means is in expanded position and held against movement in said one direction, said trigger means and said mandrel having coengageable means for moving said trigger means to inoperative position when said mandrel has moved a predetermined distance in said one direction relative to said cage to free said mandrel from the force of said resisting means resisting movement of said mandrel in said one direction.

8. The signaling device of claim 7, and control means operatively associated with said mandrel and operable to releasably hold said trigger means in said inoperative position.

9. A signaling device including: an elongate mandrel; a cage mounted on said mandrel for longitudinal movement relative thereto between first and second positions; means biasing said cage to an intermediate position between said first and second positions; sensor means carried by said cage and movable laterally relative to said mandrel between an inner retracted position and an outer expanded position; means biasing said sensor means toward said expanded position, said mandrel and said sensor means having means coengageable when said sensor means is in said intermediate position relative to said mandrel for locking said sensor means in said expanded position; means for yieldably resisting movement of said mandrel in one longitudinal direction relative to said cage when said cage is in said intermediate position; and trigger means operatively associated with said cage and said resisting means operative when said cage is in said intermediate position for causing said resisting means to yieldably resist movement of said mandrel in said one direction relative to said cage, said trigger means and said mandrel having coengageable means for moving said trigger means to inoperative position to render said resisting means ineffective to resist movement of said mandrel in said one direction relative to said cage when said mandrel has moved a predetermined distance in said one direction relative to said cage.

10. The signaling device of claim 9, and control means operatively associated with said trigger means and selectively adjustable to releasably hold said trigger means in said inoperative position.

11. A signaling device movable through a flow conductor having a plurality of longitudinally spaced internal recesses each providing a pair of longitudinally spaced annular internal facing shoulders, said signaling device including: an elongate mandrel; a cage mounted on said mandrel for longitudinal movement relative thereto between first and second positions; means biasing said cage to an intermediate position between said first and second position; sensor means carried by said cage and movable laterally relative to said mandrel between an inner retracted position and an outer expanded position; means biasing said sensor means to said expanded position, said sensor means and said mandrel having means coengageable when said sensor means is in said intermediate position for locking said sensor means in said expanded position when said sensor means move outwardly into an internal recess of a flow conductor; means for yieldably resisting longitudinal movement of said mandrel relative to said cage when said cage is in said intermediate position; and trigger means operatively associated with said cage and said resisting means operative when said cage is in said intermediate position causing said resisting means to yieldably resist longitudinal movement of said

mandrel relative to said cage when said signaling device is being moved through the flow conductor and the sensor means moves outwardly to its expanded position into an annular recess of the flow conductor and engages an internal shoulder thereof to prevent movement of said sensor means and cage through the flow conductor, said trigger means and said mandrel having coengageable means for moving said trigger means to inoperative position to render said resisting means ineffective to resist longitudinal movement of said mandrel relative to said cage upon movement of said mandrel longitudinally a predetermined distance relative to said cage after downward movement of said sensor means and said cage through the flow conductor has been arrested.

12. A signaling device including: an elongate tubular mandrel; a cage mounted on said mandrel for longitudinal movement relative thereto between first and second positions; means operatively associated with said means biasing said cage to an intermediate position between said first and second positions; sensor means carried by said cage and movable laterally relative to said mandrel between an inner retracted position and an outer expanded position; means biasing said sensor means toward said expanded position; said mandrel and said sensor means having means coengageable when said cage is in said intermediate position for locking said sensor means in said expanded position; a control rod extending through said mandrel; yieldable means for yieldably resisting longitudinal movement of the mandrel relative to said control rod; and trigger means carried by said cage and coengageable with said control rod when said cage is in said intermediate position for preventing longitudinal movement of said control rod relative to said cage, said trigger means and said mandrel having coengageable means for moving said trigger means to inoperative position to permit said control rod to move relative to said mandrel upon predetermined longitudinal movement of said mandrel relative to said cage when said cage is in said intermediate position.

13. A signaling device including: an elongate tubular mandrel; a cage mounted on said mandrel for longitudinal movement relative thereto between first and second positions; means operatively associated with said means biasing said cage to an intermediate position between said first and second positions; sensor means carried by said cage and movable laterally relative to said mandrel between an inner retracted position and an outer expanded position; means biasing said sensor means toward said expanded position; said mandrel and said sensor means having means coengageable when said cage is in said intermediate position for locking said sensor means in said expanded position; a control rod extending through said mandrel; yieldable means for yieldably resisting downward movement of the mandrel relative to said control rod; and trigger means carried by said cage and engageable with said control rod when said cage is in said intermediate position for preventing downward movement of said control rod relative to said cage, said trigger means and said mandrel having coengageable means for moving said trigger means to inoperative position to permit said control rod to move relative to said mandrel upon predetermined downward movement of said mandrel relative to said cage when said cage is in said intermediate position.

14. A signaling device including: an elongate mandrel; a cage mounted on said mandrel for longitudinal movement relative thereto between first and second positions; means biasing said cage to an intermediate position on said mandrel between said first and second positions; sensor means carried by said cage and movable laterally relative to said mandrel between an inner retracted position and an outer expanded position; means biasing said sensor means towards said expanded position, said sensor means and said mandrel having means coengageable when said cage is in said intermediate position for locking said

sensor means in said expanded position; a control rod extending through said mandrel and having a catch edge below said cage; resisting means carried by said mandrel above said cage for yieldably resisting longitudinal movement of said mandrel relative to said control rod; and trigger means carried by said cage and movable between an operative position wherein said trigger means is engageable with said catch edge of said control rod to hold said control rod against longitudinal movement relative to said cage whereby longitudinal movement of said mandrel is then resisted by said resisting means, said trigger means and said mandrel having coengageable means for moving said trigger means to an inoperative position to permit longitudinal movement of said control rod relative to said cage when said mandrel has moved longitudinally a predetermined distance relative to said cage when said cage is in said intermediate position.

15. The signaling device of claim 14, wherein said resisting means includes a pair of springs operatively associated with said control rod and said mandrel and of said springs being adapted to resisting movement of said mandrel in one direction relative to said mandrel and both of said springs being adapted to resist movement of said mandrel in a direction opposite said one direction.

16. The signaling device of claim 15 wherein said trigger means includes a trigger link mounted on said cage for pivotal movement about a horizontal axis, said mandrel having aligned vertical slots below said cage, said trigger link having a transverse plate extending through said vertical slots and engageable with said catch edge.

17. The signaling device of claim 16 wherein said coengageable means of said trigger means and said mandrel comprise cam shoulders on said plate and cam shoulders on said mandrel at said vertical slots.

18. The signaling device of claim 17 wherein said mandrel has two vertically spaced pairs of aligned vertical slots and said control rod has two longitudinal slots aligned with said two pairs of mandrel slots; and a pair of vertically spaced cross pins extending through said slots, and three spring retainer means disposed about said mandrel, one of said spring retainer means engaging one of said cross pins and one of said springs, a second of said retainer means engaging said one of said cross pins and the other of said springs, and the third of said spring retainer means engaging the other of said cross pins and both of said springs, said mandrel having means limiting downward movement of one of said spring retainer means on said mandrel.

19. The signaling device of claim 14 wherein said trigger means includes a trigger link mounted on said cage for pivotal movement about a horizontal axis, said mandrel having aligned vertical slots below said cage, said trigger link having a transverse plate extending through said vertical slots and engageable with said catch edge.

20. The signaling device of claim 19 wherein said coengageable means of said trigger means and said mandrel comprise cam shoulders on said plate and cam shoulders on said mandrel at said vertical slots.

21. The signaling device of claim 20 wherein said mandrel has two vertically spaced pairs of aligned vertical slots and said control rod has two longitudinal slots aligned with said two pairs of mandrel slots; and a pair of vertically spaced cross pins extending through said slots, and three spring retainer means disposed about said mandrel, one of said spring retainer means engaging one of said cross pins and one of said springs, a second of said retainer means engaging said one of said cross pins and the other of said springs, and the third of said spring retainer means engaging the other of said cross pins and both of said springs, said mandrel having means limiting

downward movement of one of said spring retainer means on said mandrel.

22. A signaling device including: a tubular mandrel; a cage mounted on said mandrel for longitudinal movement thereon between first and second positions; means biasing said cage to an intermediate position on said mandrel between said first and second positions; a pair of sensor members each mounted on said cage for pivotal movement about a vertical axis between inner retracted positions and laterally outer expanded positions; means biasing said sensor members toward said outer positions, said sensor members and said mandrel having means coengageable to lock said sensor members in said expanded positions when said cage is in said intermediate position; a control rod longitudinally movable in said mandrel and having a pair of facing vertically spaced substantially horizontal facing catch edges adjacent its lower end, said mandrel having a pair of aligned vertical slots adjacent the lower end of said control rod; a trigger link pivotally mounted on said cage and having a transverse plate extending through said slots and receivable between said catch edges when said cage is in said intermediate position; means yieldably biasing said trigger link to position wherein said transverse plate is between said catch edges; means on said trigger link and said mandrel for pivoting said trigger link to move said plate from between said catch edges upon predetermined longitudinal movement of said mandrel relative to said cage in either longitudinal direction when said cage is in said intermediate position, said mandrel and said control rod having upper and lower sets of aligned vertical slots above said cage; an upper cross pin extending through said upper set of slots and a lower cross pin extending through said lower set of slots; an upper spring retainer means engaging said upper cross pin and a lower spring retainer means engaging said lower cross pin; a middle spring retainer means engaging one of said cross pins; an inner spring engaging one of said lower and upper retainer means and said middle retainer means and an outer spring engaging said upper and lower retainer means; means limiting movement of said upper and lower retainer means on said mandrel away from each other, said springs resisting movement of said cross pins toward one another, said upper cross pins and said control rod being engageable to limit downward movement of said control rod relative to said upper cross pins, and lower cross pin and said control rod being engageable to limit upward movement of said control rod relative to said lower cross pin.

23. The signaling device of claim 22, including connector means on the lower end of said mandrel movable upwardly relative thereto; and control means on said mandrel engageable with said trigger link to hold said trigger link in inoperative position wherein its plate cannot move between said catch edges, said control means being movable on said mandrel upon movement of said control means relative to said mandrel between operative position wherein it is engageable with said trigger link and an inoperative position wherein it is not engageable with the trigger link.
